UNITED STATES PATENT OFFICE.

RUDOLPH F. STEHLIK, OF CHICAGO, ILLINOIS, ASSIGNOR TO AUTOMATIC ELECTRIC INC., OF CHICAGO, ILLINOIS, A CORPORATION OF DELAWARE.

TELEPHONE SYSTEM.

Application filed May 7, 1926. Serial No. 107,336.

The present invention relates in general to telephone systems, but is concerned more particularly with telephone systems of the type in which so-called "finder switches" or "line finders" are employed to connect an idle trunk line with a calling subscriber's line; and a special object of the invention is an improvement in such systems which permits the grouping of the subscribers' lines into relatively large groups which are accessible through two or more interrelated groups of finder switches.

In the embodiment of my invention, I propose to use a finder switch of the two-motion type, i. e., a switch whose wipers are moved first in a vertical direction and then in a horizontal direction to the desired bank contact set. Moreover, I propose to equip the finder switches with a double set of wipers, and a double set of banks through which the finder switch will have access to 200 lines. Moreover, I propose to use a finder switch of the directive type, i. e., a switch which is directed to the bank contacts of the calling line by an external sending mechanism, rather than a finder of the hunting type which searches for a particularly marked contact designating the calling line. Associated with and common to a group of finder switches I provide a control equipment comprising a sending mechanism, a sequence switch for controlling the same, register relays for associating a control equipment with the group containing the calling line, control relays for controlling the sender, sequence switch and register, and an allotter switch through which the control equipment is associated with the finders of the group one at a time. For every 200 line group of subscribers' lines, I provide two groups of finder switches of the above mentioned type, and two separate control units. In the normal working of the system, calls from the first hundred lines, or A group, are handled through the normally connected wipers of the first or A group of finder switches, those switches being controlled in turn by the first of the control equipments; and calls from the second hundred lines; or B group, are handled through the wipers of the second or B group of finders, which in turn are controlled by a second control equipment. These two finder groups and their respective associated control equipments, are inter-related and interconnected so that the 200 line group of subscribers' lines is served jointly by the two

finder groups, as will be set forth hereinafter.

One of the objects of the invention is to provide circuit means such that if two simultaneous calls are started in one of the one hundred line groups mentioned above, a finder switch in the first choice group will be controlled by the first choice control equipment to connect with one of the calling lines, and a finder switch in the second choice group will be controlled by a second control equipment to connect with the other of the calling lines, the second finder being started as soon as the first control equipment has "switched through" provided no line in the second group is calling at the instant.

If two simultaneous calls are initiated in one line group at the same time that a call is initiated in the other line group, one call from each line group will be immediately handled by the finder equipment which is first choice to that line group. The second call in the first mentioned line group will be handled by the finder control equipment which first restores to normal.

Another object of my invention is to provide circuit arrangements whereby if the finder, operated in response to a calling line from the group of lines to which it is first choice, fails to connect with that line due either to a mechanical or electrical defect in the finder or control equipment, the mechanism involved will be immediately released, and a finder in the second choice group will be controlled by the second control equipment to connect with the calling line. If the trouble is of such nature that the control equipment is prevented from restoring to normal, all subsequent calls are handled by the second control equipment, and an alarm is brought up to point out the trouble in the first control equipment.

Another object of my invention is to provide a manual key which is operated to disconnect either group of control equipment in case that equipment is in need of adjustment or repairing, in which case calls from either group of lines are handled by either group of finder switches under the control of the one remaining group of control equipment, that is, the finders are all grouped together in one large group under the control of the one control equipment which is in working order at the time.

Another object of my invention is to provide an all-finders busy relay in the control

equipments, that relay being energized as long as an idle finder remains in the group controlled by the equipment. When the last finder in the group is seized and operated the 5 all-finders busy relay deenergizes, and cuts the control equipment momentarily out of service so that all calls from either group of lines are handled by the other finder group and control equipment.

10 As a further object of my invention I provide separate fuses for the control equipment switching relay and fuse the all-finders busy relay in common with the control equipment and senders, so that in the event that the latter fuse blows, disabling the sender and control equipment, the all-finders busy relay deenergizes and the control equipment switching relay energizes to transfer subsequent 15 calls to the other finder and control equipment group.

20 In accordance with the requirements of established telephone practice I provide discriminating tones by means of which the toll recording operator is informed as to the classes of toll service to which the calling subscriber is entitled. In making this provision, 25 I arrange the discriminating tone circuits so that the proper tone will be given independent of the finder group through which the 30 call is handled.

35 A further object of my invention is to provide an improved sender circuit in which a common interrupting device sends impulses simultaneously to the motor magnet of the finder switch and to the motor magnet of the stepping control switches of the sender, the interrupter equipment being controlled by a stepping relay which is controlled by rever- 40 tive pulses from the finder switch magnet and from the sender switch magnet. In case either the finder switch or the sender switch magnet fails to operate properly and does not deliver its revertive pulse, a slow operating relay timed to operate after a definite 45 interval, switches the call to the other group.

50 As a further object of my invention I provide a new and improved circuit for restoring the counting switches of the sender switches to normal. Heretofore such switches have been restored through the medium of a wide wiper which bridged the contacts over which it passed and through which the magnet circuit was closed. This wiper was subject to considerable wear, which greatly shortened 55 the life of the switch. In improving this feature I use a "return to normal relay" which controls the magnets of the senders. That relay is differentially wound and when the wipers of the senders reach the next to normal 60 contact set, a circuit is closed through the second winding of the relay, to deenergize it and open the magnet circuits. The sender switch magnets deenergize, advancing the wipers one step into the normal position.

65 Further objects of the invention, not spec-

ifically enumerated here, will be apparent from the detailed specification and claims which follow.

The drawings comprising Figs. 1 to 8, inclusive, when arranged with Figs. 1, 2, and 3 in a horizontal row with Figs. 4, 5, and 6 in a second horizontal row directly beneath the first with Fig. 7 beneath Fig. 5, and Fig. 8 beneath Fig. 7, with all corresponding lines in alignment, show sufficient circuit details to enable a clear understanding of the invention. With the drawings so arranged the equipment shown in Figs. 3 and 6 and on the right hand side of Figs. 5, 7, and 8 comprises a finder and control equipment group which will be 70 hereinafter designated as group A; and the equipment shown in Figs. 1 and 4, and on the left hand side of Figs. 5, 7, and 8 comprises a group of finders and control equipment 75 hereinafter designated as group B. Fig. 2 shows the line equipment of a 200 line-group of subscribers' lines, those lines being seized by the finders in either group A or group B. However, the normal running of the system 80 the lines A¹ and A² etc., in the 100 line-group 85 that is, numbers from 100 to 199, inclusive, will be seized by finders in group A, those finders being the first choice of that group of lines. Similarly, lines B etc. in the 200 line-group that is numbers from 200 to 299, includ- 90 95 100 105 110 115 120 125 130 135 140 145 150 155 160 165 170 175 180 185 190 195 200 205 210 215 220 225 230 line switch whose wipers are in no normal position but move in a forward direction only, and whose wipers are advanced by a back-acting armature arrangement, that is the wipers are advanced when the magnet of the switch deenergizes rather than when the magnet energizes. The finders of group B, such as F^2 for example, are accessible to the control switch through the banks of the finder allotter FA^2 , the allotter serving to connect the finders one at a time to the control mechanism which directs them in search of a calling line. In Fig. 1, I show conductors 74, 75, 84, 85, connected to pins bearing similar numbers with the exponent 1. In Fig. 3, I show similarly numbered pins with the exponent 2. I have made this arrangement to simplify the drawings, in practice these conductors will be connected through without the use of the pins.

In Fig. 4, I show the control mechanism employed to direct the finder such as F^2 to a calling line. The mechanism comprises a sequence switch SQ^2 which is mechanically similar to the finder allotter FA^2 , and which is instrumental in directing the sequence of the operation of the finders F^2 with the sequence switch in the first position, impulses generated by the impulsive mechanism contained in the control equipment CR^2 are directed to the vertical magnet of the finder, and with the sequence switch SQ^2 in the second position impulses are directed to the rotary magnet of the finder. When the sequence switch moves to its third position at the termination of the rotary impulsive, the finder F^2 is switched through to seize the calling line, the finder allotter FA^2 is stepped ahead one step to associate the control equipment with the next finder of the group, and the control equipment and sequence switch SQ^2 are subsequently returned to normal in readiness for the next call.

In Fig. 2 are shown three subscriber stations B, A^1 and A^2 , and their associated individual line equipment through which they control the finder equipment when calling. Substation B which is designated as No. 225 controls through the relays 201 and 202 the finder group B, in the normal working of the system. The relay 202 energizes responsive to the removal of the receiver from the switchhook in the substation. To start the finder control mechanism B and to strap the banks of that mechanism sender to direct the finder F^2 to the contacts of the calling line.

Substations A^1 and A^2 designated as Nos. 125 and 115, respectively, control through the relays 204 and 206, inclusive, the finder group A in the normal working of the system. Relays 204 and 206 energize responsive to initiation of a call from their respective substations to start the group A mechanism and to strap the sender banks thereof to drive the finder F^1 to the calling line. It will be

noted that in Fig. 2, I show the bank contacts of the line A appearing both in the banks of the finder F^1 and the finder F^2 , and that I show normal cables leading off to the connector bank.

In Fig. 3, I show a finder F^1 of the finder group A, connected to a selector S^1 . The finder F^1 and the selector S^1 are identical with the finder F^2 and selector S^2 explained hereinbefore. In reality the selectors S^1 and S^2 are in the same group, their wipers having access to the same trunk lines. In Fig. 3 I also show a finder allotter FA^1 whose functions are the same as those of finder allotter FA^2 . It will be noted that the finder allotters FA^2 and FA^1 have access to all of the finders in both groups, that is, the finder allotter FA^1 has access to finders in group A through one-half of this bank, and access to finders in group B through the other half of its bank. Similarly finder allotter FA^2 has access to both groups of finders. This interconnecting of the finder allotters FA^1 and FA^2 is made in accordance with one of the objects of the invention to permit the control of all of the finders of the system by one control equipment, that is, the two groups of finders are thrown into one large group and controlled by one control equipment.

In Fig. 6, I show the control equipment CR^1 arranged to normally control the finders in group A, this equipment the sequence switch SQ^1 and the relays associated with it. This equipment is a duplicate of the equipment CR^2 shown in Fig. 4 and explained above. In Fig. 6, I also show supervisory lamps 611, 612, and 613, which are actuated during the course of operation of the finder groups to apprise the attendant of their working condition.

In Fig. 5, I show marking relays 501 and 502 which are energized to associate the start wire circuit with the control group B when a call is initiated in either of the line-groups A or B. Relays 503 and 504 similarly associate a start circuit of the lines in groups A and B with the control group A responsive to the initiation of a call. In Fig. 5 I also show a two-position manual key which is thrown in one direction or the other to cut out a faulty control equipment and to switch the start circuits so that calls in either group are handled by the one remaining control equipment.

In Fig. 7, I show the rotary stepping control switch RSB comprising wipers 705-707, which is associated with the control equipment B. This switch is mechanically similar to the sequence switch and finder allotters enumerated above and is stepped in synchronism with the magnets of the finder to count the impulses delivered thereto instrumental and positioning the wipers on the desired bank contact. On the right of Fig. 7 I show a similar rotary stepping control

switch RSA comprising wipers 710-712, which is associated with the control equipment A to perform a similar function. It will be noted that the banks of the two stepping control switches are multiplied together.

In Fig. 8, I show, on the left of the figure, a vertical stepping switch VSB comprising wipers 805-809, inclusive, which is associated with the group B control equipment and which is energized simultaneously with the vertical magnet of the finder F² to count the impulses delivered thereto instrumental in setting the finder in position to connect with the called line. At the right of the figure I show a vertical stepping control switch VSA comprising wipers 812-860, inclusive, which is associated with the control equipment of group A to perform a similar function. As in the case of the rotary stepping control switch, the banks of the vertical stepping control switch of group A are multiplied to the banks of the vertical stepping control switch of group B for a purpose which will be hereinafter set forth.

Assume for the moment that line 225 initiates a call, and at the moment the finder and control equipment of group A is unoccupied. Responsive to the removal of the receiver from the substation, relay 206 energizes and closes the start wire circuit by the replacing of ground on conductor 257, at ground energizing the register relay 504 to assign the call to the group A finder equipment. Relay 504 energizes in series with the supervisory relay 608 of the control equipment CR¹, the latter relay energizing and closing supervisory circuits which will be enumerated later. Responsive to the closure of relay 504 sender start circuits are prepared by energizing start relay 604, which in turn energizing the pulsing relay 607 to complete the pulsing circuit. Relay 607 completes a circuit to the vertical magnet 312 of the allotted finder F¹, energizing that magnet to lift the wipers of the finder F¹ one vertical step. When the vertical magnet is completely energized it closes a circuit for the revertive pulse control, that circuit extending through the left hand winding of the shunt field stepping control relay 605. Relay 605 is so constructed that it will not operate its armature when energized through only one of its windings, and does not energize at this time. The energization of relay 607 also closes a circuit for the motor magnet 810 of the vertical stepping control switch VSA, that magnet energizing in preparation to advancing its wipers. When the magnet 802 is completely energized, it closes a circuit for the revertive control pulse, that circuit including the right hand winding of the stepping relay 605, since both windings of the relay 605 are now energized the relay attracts its armature and opens the above circuit to the vertical magnet of the finder F¹ and to the multiple mag-

net of the vertical stepping control switch VSA, permitting those magnets to deenergize, the former dropping back preparatory to taking in an additional step, and the latter dropping back to advance the switch wipers one step. When both the vertical magnet of F¹ and the motor magnet of the switch VSA have deenergized the circuit of relay 605 will be opened and that relay will restore after a brief interval, to again close the pulsing circuit to those magnets.

Since the substation A² is number 225 in the finder switch banks it is necessary that the vertical magnet of the finder F¹ be stepped up two steps to bring the wipers opposite the second level of the switch bank. The energization of relay 206 closes circuits closed through the wipers of the vertical stepping control switch so that when the relay 605 again closes the above enumerated circuit it closes an additional circuit to the magnet 610 of the sequence switch SQ¹. Relay 605 is energized in the above explained manner to terminate the pulse, a vertical magnet of finder F¹ and the motor magnet of the vertical stepping control VSA energizing as before. Magnet 610 of the sequence switch SQ¹ being also energized, deenergizes upon the energization of relay 605, and advances the sequence switch wipers 653 to 655, inclusive, one step. When the magnets have all deenergized, wipers of the finder F¹ are standing opposite the second level of banks, wipers of the sequence switch SQ¹ are in the second position, and the wipers of the vertical stepping control are standing on the second bank contact. When the relay 605 deenergizes it again closes the pulsating circuit which is now directed to the rotary magnet 313 of the finder F¹ and to the motor magnet 702 of the rotary stepping control switch RSA, comprising wipers 710 to 712, inclusive, those magnets energizing to advance the finder allotter wipers one step and to count off the impulses delivered thereto. When both the rotary magnet and the motor magnet of the stepping control switch are fully energized, relay 605 is again energized by the revertive pulses to permit the magnets to restore to their normal position.

From the foregoing description it will be apparent that the interval between the vertical and rotary impulse transmission is no longer than the interval between successive vertical impulses. As the vertical magnet is being operated to elevate the shaft and wipers, the latter are set to vibrating, that vibration attaining considerable amplitude if the shaft is elevated to a high level, such as the ninth or tenth. It is impossible to rotate the wipers into the selected level while they are vibrating and therefore I have arranged the shaft so that two rotary steps are necessary to bring the wiper into engagement with the first contact in the bank levels. The

time required for this extra rotary step when added to interval between impulses is sufficient to permit the wipers to come to stop vibrating, so that when they are moved into 5 the level they will properly engage the contacts.

Returning now to the call in progress, since the calling line is No. 25, etc. six rotary steps will be necessary, the magnet and stepping 10 relay 605 working together in the above manner advance the wipers to the fourth bank position. At this time a circuit is closed through springs of relay 206 so that when the impulse is delivered to the magnet it is 15 also delivered to the magnet 610 of the sequence switch SQ¹. That magnet energizes preparatory to advancing the wipers of the switch into the next position. At the completion of the sixth pulse the wipers of the 20 finder F¹ are standing on the fifth bank contact set which leads to the calling line A¹. When the sequence switch SQ¹ positions its wipers in the third position it prepares the switching through circuit which is closed as 25 soon as the relay 605 restores, that circuit energizing the relay 306 to connect the finder F¹ with the calling line. The energization of relay 306 closes the calling loop circuit to the line relay 305 of the selector S¹ energizing 30 that relay preparatory to subsequent control by the calling subscriber. Relay 306 also closes a circuit for the relay 203 of the line relay group associated with the calling line, that relay energizing to disconnect the relay 35 204 to permit it to restore to normal. The closing of the switch through circuit completes the functions formed by the control group and setting the finder switch F¹ on the contacts of the calling line, that equipment 40 restoring to normal in readiness for the next call.

When relay 607 of the control group CR¹ was energized, it closes a circuit for the relay 602 which energizes and locks itself to the upper winding of the relay 601. Relay 607 also closes the circuit through the lower winding of the relay 601 which energizes and switches the start circuits of the remaining lines in group A so that in the event one of those lines should call while the equipment CR¹ is occupied it would be handled by equipment CR² which will be explained presently. Relay 607 also closes a circuit for the magnet 314 of the finder allotter FA¹ energizing that magnet preparatory to advancing the wipers to the next step. When the finder F¹ is switched through to the calling line, the circuit of relay 607 is opened permitting that relay to restore and open the circuit of magnet 314, which deenergizes and advances the wipers to the next set of contacts which leads to another finder such as F¹. The finder allotter FA¹ remains on the next contact set if a finder associated therewith is idle, and steps off of that contact set if the

finder associated therewith is busy searching under the control of a local circuit for the first idle finder in the group. Relay 602 being locked in series with the upper winding of relay 601 holds the two relays in an energized position after relay 607 deenergizes. When the completion of the switch through operation the circuits are closed for the motor magnets of the vertical and rotary stepping control switches, under the control of 70 a local interrupting contact, which causes the magnets of those switches to act in a buzzer like manner to advance the wipers to their normal position. When the wiper 712 and 75 812 of the rotary and vertical stepping control switches, respectively, reach the next to the normal position, they close a circuit through the lower winding of the relay 602 and the motor magnet 702 and 802, these 80 magnets being in parallel in the circuit. Relay 602 is differentially wound and the lower winding is so proportioned that when the two magnets are energized in parallel through it, the flux it produces neutralizes the flux of the upper winding and permits the relay to deenergize. The deenergization of relay 602 unlocks relay 601, thereby 85 restoring the control equipment CR¹ to normal in readiness for the next call. 90

A call originating in substation B, which is in the 200 line group which is normally served by the control and finder group B energizes the relay 202 throwing the ground on the start conductor 256 to energize the register relay 501 in series with the supervisory relay 402. The energization of relay 501 closes a circuit for start relay 406 which energizes to start the finder control equipment CR² in search of the calling line. Relay 406 closes the circuit for relay 403 which energizes and delivers impulses to the vertical magnet of the finder F² and to the motor magnet of the vertical stepping control switch VSB to step and control the vertical motion of the wipers of the finder F² in the above described manner. Shunt field relay 405 energizes to terminate the pulse as before described, in connection with CR¹. Relay 202 closes a circuit so that when the second pulse is delivered to the magnets of the counting switch and vertical magnet of the finder, a circuit is also completed for the magnet 410 of the sequence switch SQ², energizing that magnet preparatory to advancing the wipers to shift the circuit from the vertical magnet and control to the rotary magnet and control. At the termination of the second impulse the sequence switch is advanced and the wipers of F² are standing opposite the second level of the bank in readiness to be rotated into that level to the contacts of the calling line. When relay 405 again deenergizes the next impulse is sent to the rotary magnet thereto and to the magnet of the rotary stepping control switch RSB to advance 115 120 125 130

the wipers F^2 and RSB, finally bringing the wipers F^2 to rest on the bank contacts of the desired line. The motor magnet 410 of the sequence switch is also energized in multiple with the rotary magnet on the last impulse over a circuit completed through the energized relay 202. When the relay 405 energizes after the last impulse, the sequence switch steps to its third position to connect up the switch through circuit which causes the finder F^2 to seize the calling line. With the sequence switch in a third position, the relay 405 remains in its normal position, slow-to-pull-up relay 404 energizes and closes the circuit for the motor magnet 14 of the finder allotter FA^2 preparatory to advancing the finder allotter in search of the next idle finder. Relay 404 completes the circuit for switching relay 409, which energizes and opens the circuit of start relay 406 preparatory to restoring the control mechanism to normal. Relay 404 also closes a circuit through the upper winding of relay 408 energizing that relay which locks itself through the upper winding of relay 409 to control the returning of the counting switches to normal in readiness for the next call.

Returning now to the operation of the finder control group equipment A while connecting with the line 225, and assuming that after the station A^2 initiated a call and before the finder F^1 connected with the line, subscriber at station A^1 removes his receiver preparatory to making a call. Under these conditions the subscriber at station A^1 will be delayed slightly in making this call, because no finder equipment is available at the instant and consequently his line will not be connected with the first selector immediately. The delay however is momentary existing only until the control equipment sequence switch SQ^1 moves into the third or switch through position. At this time the locking circuit of register relay 504 is opened, the switching relay 601 is energized, so that the start wire circuit grounded by the energization of relay 204 is completed through to the relay 502, energizing that relay to register the call in the group B equipment. The equipment CR^2 is ready to immediately start a finder such as F^2 in search of the calling line through the second choice or A set of wipers. The energization of relay 502 closes a circuit for the wiper switching relay 7 of the finder F^2 , energizing that relay so that when the wipers are positioned on the bank contact the finder will be connected through to the line A^2 . It will be noted that the group B equipment picks up the overflow calls in the group A before the group A equipment has completed its cycle of operation in connecting with the first line calling. As soon as the sequence switch SQ^1 has moved into the switch through position, the start circuit to the group B equipment is completed so that

equipment may be functioning while the control equipment CR^1 is restoring to normal while the finder allotter FA^1 is preselecting the next finder to be used.

Similarly if while a call from line 225 is being found by the group B finder equipment, a call is originated by a second line in the B line group, that call will be handled by the group A finder equipment through the second choice or B set wipers as soon as the sequence switch SQ^2 has moved into the switch through position, at which time relay 409 will energize, relay 501 will deenergize to switch through the start circuit so that the ground placed on the start wiper by line relay such as 202 will energize the register relay 503 to register the group B call in the group A finder equipment. The energization of relay 503 closes a circuit for the wiper switching relay 307 of the finder F^1 , which energizes and connects the second choice wipers 270 to 272 so that when the wiper sets are positioned on the bank contacts, the finder F^1 will be connected to the calling line in the B group.

In the foregoing general explanation of the workings of the system of my invention, I have assumed that the equipment was functioning properly. Assume now that some mechanical or electrical fault exists, and that the vertical magnet of the finder F^1 fails to return the reverfive pulse to terminate the impulse delivered to it by the control equipment CR^1 . It will be noted that the energization of relay 607 prepares a circuit for the slow to pull up relay 606, and the circuit being under the control of springs 637 of the shunt field stepping relay 605. This shunt field relay will not operate unless both of its windings are energized, the circuit through springs 637 is not interrupted and the slow-to-pull-up relay 606 energizes after a brief interval. The energization of this relay completes a circuit for the switching relay 601 and unlocks the start relay 604. Register relay 504 will deenergize after a brief interval and the start circuit ground over which relay 504 was initially energized will be led over a circuit through the working contacts on the switching relay 601 to the winding of relay 502 of the group B equipment so that the call will be picked up by that equipment. The energization of relay 603 also completes the release circuits of the finder group A, and instructs the finder allotter FA^1 off of the contacts leading to the faulty finder. In this case of trouble no supervision would be given to the station attendant, as the trouble is not very serious, merely throwing out of service the one finder F^1 .

Assume for an instant that the motor magnet 802 of the vertical stepping switch was burned out and that switch could not be stepped to count the pulses delivered to the vertical magnet of the finder. The mag-

net 802 would therefore not return its re-
titive pulse to the right hand winding of
relay 605 and the slow-to-pull-up relay 606
would be energized to transfer the call to the
5 group B equipment in the manner explained
above. Relay 606 would again close the cir-
cuits for returning the equipment to normal
and since the magnet 802 is burned out that
switch would not return to its normal posi-
10 tion, consequently the control equipment CR¹
would not be released and after an interval
a signal would be brought up to notify the at-
tendant that the control equipment was tied
up and out of service. Calls coming into this
15 system during this interval would be handled
by the control equipment CR² and the finders
of the group B.

A burned out magnet such as mentioned
above would disable the control equipment
20 CR¹ for a relatively long period of time dur-
ing which repairs were being made. The at-
tendant upon noting the signal that the con-
trol equipment CR¹ is out of service will oper-
ate the key K to cut the control equipment
25 CR¹ permanently out of service, and divert
the start circuit from both the A and B
groups of subscribers' lines to the B control
equipment so that all calls from both groups
are handled by the one equipment. The op-
30 eration of the key K also completes circuits
so that the control equipment CR² can con-
trol the finders of the A group as well as the
finders of the B group which are normally
controlled by it. It will be noted that in the
35 banks of the finder allotter FA² the contacts
of the first half of the banks lead to the find-
ers in the B group, and that the contacts in
the second half of the bank lead to the finders
in the A group. When the key is operated to
40 cut-out one of the control equipments the
finder allotter such as FA² searches for an
idle finder in both the A and B groups. Thus
it will be seen that in case of emergency the
operation of the key K throws the two groups
45 of finders into one large group which is con-
trolled by the remaining control equipment.

Similarly if the control equipment CR² be-
comes defective the signal will be given to
the attendant and he will operate the key K
50 in the opposite direction by transferring the
start circuits from the B group over to the
A control equipment and throwing the two
groups of finders together so that finder al-
lotter FA¹ will have access to the entire num-
55 ber of finders.

In the control equipment CR¹ is an all
finder busy relay 603 which is normally ener-
gized over a circuit completed through the
grounded springs 333 of the finder F¹, and
60 the other finder of the group in multiple. As
long as there remains one idle finder in the
group A, relay 603 will be energized, but
when the last idle finder in the group is op-
erated, the relay 603 deenergizes and com-
65 pletes a circuit for the switching relay 601

which energizes and prepares the start wire
circuit so that subsequent calls in the group
A lines will be picked up by the group B
finder equipment.

Constantly energized relay 603 is fused in
common with the control and finder equip-
ment, the switching relay 601 however is
fused separately so that in the event that the
main fuse to the control equipment CR¹ is
blown out by an over load, the relay 603 will
70 deenergize and close a circuit for relay 601
which with its separate fuse will not be af-
fected by the blown main fuse and will ener-
gize to transfer the call to the group B.
Group B is of course similarly equipped, the
75 constantly energized relay being relay 407
which is used in common with the equipment
CR² and the switching relay 409 is provided
with a separate fuse as shown.

In order to give satisfactory service of a
more or less special nature, such as toll service,
it is necessary that the subscriber's lines be
classified into certain groups, and that the
toll recording operator be informed as to the
80 group to which the calling line belongs. 85
When a system such as I have described in the
present invention, discriminating tones can
be readily given to the recording operator
over the release or holding trunk in the usual
manner. As shown in Fig. 2 the finder bank
90 contacts appear in the same relative position
as the connector bank contacts, that is, line B
which is assumed to be No. 225 appears in
the twenty-fifth bank position of the 200 line
finder group as well as in the twenty-fifth 95
position of the 200 line connector group.
The drawings are so shown merely to avoid
unnecessary complication, and it will be
readily appreciated that by the introduction
100 of a distributing frame between the sub-
scriber's line and the finder equipment, the
subscriber's line can be connected to the finder
equipment as the occasion demands without
any regard to the connector bank numbers
105 of the line, that is, the directory listing of
the line. In the embodiment of this idea I
propose to group all of the subscriber's lines
having a certain class of toll service allowed
to them in the B group and all of the lines
110 having a different class of service allowed to
them in the A group, and have arranged the
tone accordingly. Referring now to Fig. 1
it will be noted that tone one is normally
connected to the rerelease trunk conductor 68
115 through the normal contacts of the switching
relay 7 and the make contacts of the switch
through relay 6. The tone number one will
be picked up by the toll recording operator
to ascertain the class of service allowed to the
120 calling subscriber. If for some reason the
subscriber at station B is reclassified as re-
gards to toll service, his finder bank number
might be changed to 125 or any other num-
ber in the 100 group, by simply lifting the
125 jumpers and transferring them to the as-
130

signed number. In that case the subscriber at B upon making the call would be connected to the finder F^2 through the other set of wipers under the control of the energization 5 of relay 7. Relay 7 energizes and connects the tone No. 2 through the springs 45 of the switching relay 6 to the release conductor 68, to inform the toll recording operator that the subscriber is entitled to the class of service 10 designated by tone 2.

Having thus described my invention in general I will now proceed with a detailed description of its operation. Assume that the subscriber at station A¹ whose finder bank 15 number is 125 initiates a call. When the receiver R is moved from the hook switch H a circuit is closed for the relay 204, traceable from ground on springs 219 through the hook switch, receiver, transmitter and calling device of the substation A¹ through springs 218 through the winding of relay 204 to grounded battery, energizing the relay to initiate the call. The energization of relay 204 at springs 217 puts the ground on the start wire conductor 25 to energize the start relay in the finder control group to be used in picking up the call. Assume for the moment that the control group CR¹ is idle at the moment, in which case it will be operated to pick up the call since 30 it is the first choice of the group A, which contains the calling line A¹. Accordingly relay 204 closes a circuit for the register relay 504 and the supervisory relay 608 of the control equipment CR¹ that circuit being traceable from ground and spring 217, conductor 257, through springs 544, conductor 585, through springs 520, conductor 562, through spring 621 and its break contact, conductor 563, through springs 536, through the winding 40 of relay 504 to conductor 568, through the winding of relay 608 to grounded battery. Relays 504 and 608 energize over this circuit, the latter to open at springs 648 the release magnet circuit of the finder F^1 prevent 45 its operation at this time and to close at springs 649 a circuit through the supervisory lamp 613 to indicate that the control equipment CR¹ is employed at the moment. Relay 506 upon energizing closes at springs 543 a circuit for the start relay 604, traceable from ground through relay 604, conductor 674, through springs 623 and 624 and their respective break contact in multiple to conductor 566, through springs 543, through relays 504 and 608 to battery. Relay 604 is short circuited by the start conductor ground on spring 543, until relay 504 is fully energized to break the start circuit at springs 544. Relay 604 then energizes. Relay 604 upon 55 energizing closes at spring 633, 634, and 635 and their respective make contacts, circuits which will be explained in detail hereinafter. Relay 604 also closes at springs 636 a circuit for the relay 607, the latter relay energizing 60 to start the finder control equipment in opera-

tion. The energization of relay 607 closes at springs 644 a circuit through springs 637 and the upper winding of slow operating relay 606 through grounded battery. In the normal operation of the system, however, relay 606 70 does not energize at this time because its circuit is opened at springs 637 by the operation of relay 605 in a manner that will be apparent presently. Relay 607, springs 646 and springs 647 closes the impulsive circuit over which the magnets of the finder F^1 and of the counting switches VSA and RSA will be energized to position the wipers of the finder switch F^1 upon the banks of contacts of the 75 calling line.

80

The first vertical impulse.

The operation of spring 647 closes a circuit from ground through springs 647, springs 639, through the wiper 654 of the sequence switch SQ¹, that wiper now being in engagement with the first bank contact or with the bank contact multiplied thereto, conductor 662, through wiper 353 of the finder allotter FA¹, that wiper now being in engagement with the first bank contact leading to the finder F^1 , conductor 356, through the winding of the vertical magnet 312 to grounded battery, energizing the vertical magnet to elevate the shaft carrying the 90 wiper groups A and B through one vertical step. The operation of the vertical magnet produces other changes in the finder F^1 which will be explained in detail later. The operation of spring 646 of relay 604 closes a circuit from ground through springs 646, spring 638, through wiper 655 of the sequence switch SQ¹, that wiper also being in engagement with the first bank contact or a contact multiplied thereto, conductor 578 through 100 the winding of the magnet 802 of the switch VSA to grounded battery. The ground on conductor 578 is also conducted through springs 547 to conductor 582, this latter circuit being without effect at this time. The 105 operation of magnet 312 of the finder F^1 closes a circuit from ground through springs 530 to the conductor 360, spring 528 and its break contact, conductor 564, thence over two paths in parallel one through the 115 resistance 614 to grounded battery, and the other through the right hand winding of relay 605 to grounded battery, energizing the relay 605. The relay 605 being of the shunt field type does not operate its armature when 120 energized through only one of its two windings, so the energization of relay 605 as explained above is without effect unless the other winding is energized. The operation of the magnet 802 of VSA closes a circuit from ground through springs 811, conductor 575, over two branches in parallel, one through resistance 615 to grounded battery, and the other through the right hand winding of relay 605 to grounded battery. The relay 605 125 130

now energizes, both of its windings are energized, and operates its armatures to open springs 637, 638, and 639. The operation of springs 637 at this time prevents the energization of relay 606 as indicated above for a purpose which will be detailed hereinafter. The operation of springs 638 opens the circuit of the magnet 802 which was traced thereto, permitting that magnet to deenergize and advance the wipers 812 to 916 of the switch VSA one step, and to remove the ground from the circuit of the right hand winding of relay 605 at spring 811. The operation of spring 639 opens the circuit of the vertical magnet 312 which was traced thereto, permitting the vertical magnet to drop up in readiness for the next pulse, and to remove at spring 330 the ground from the circuit of the left hand winding of relay 605. The two windings of relay 605 are made slow to deenergize by the shunting of the windings through the resistances 614 and 615, respectively to battery, thereby causing relay 605 to remain in its energized position sufficiently long to hold the circuit of the above magnets open long enough to permit the armatures to restore to normal and perform the functions indicated. By adjustment of the value of resistances 614 and 615 the pulse ratio delivered to the magnet can be varied to suit the requirements of the switch structures controlled thereby.

The last vertical impulse.

Since the calling station A¹ has the finder bank number 125, its bank contacts appear in the second level of the 100 group, and consequently two vertical impulses are all that are required to elevate the wipers of the finder F¹ in position to subsequently connect with the line contacts. If some other number were calling the foregoing impulsion would continue to elevate the wipers opposite the level containing the contacts of the calling line, the operation being exactly as detailed above and need not be repeated. Returning now to the present call when the magnet 605 deenergizes at springs 638 and 639 it again closes the circuits for magnet 802 and 312, respectively, energizing those magnets as before. Since the contacts of the calling line are in the second bank level, the the ground placed on the conductor 578 by the springs 638 traverses a circuit through the springs 548, conductor 582, through the tenth A common of group A, conductor 260, through springs 215 of the line relay 204 to conductor 261, through the second A common of group A, wiper 814 now engaging the second contact in its bank, conductor 584, through springs 545 to conductor 576 through the first contact in the bank of SQ¹, through wiper 653 which are in engagement therewith, through the winding of magnet 610 to grounded battery energizing the magnet 610 preparatory to advancing the wipers 653-655, inclusive, of the sequence switch SQ¹ to the next bank contact. When the relay 605 is then energized responsive to the complete operation of magnet 312 and 802, at springs 638 and 639 it again opens the circuit of magnet 802 and 312 and in addition opens a circuit just traced for the magnet 610, permitting these three magnets to deenergize the former performing the same functions as before and the latter advancing the wipers 653 and 655 of the sequence switch SQ¹ into the second position from which it controls subsequent impulses, directing them to the rotary magnet 313 of the finder F¹ and to the magnet 702 of the rotary stepping control switch RSA as will now be explained.

The first rotary impulse.

Since SQ¹ has been advanced to the second step, the circuits for the vertical magnet and the vertical stepping control are opened and when the relay 605 falls back after a brief interval it closes a circuit for the rotary magnet 313 and the rotary stepping control switch RSA. The rotary circuit being traced from ground on springs 647, through spring 639 and its break contact, wiper 654 of SQ¹, the second bank or the contacts multiplied thereto, via conductor 661 through the wiper 354 of FA¹, through the winding of the rotary magnet 313 to grounded battery, energizing that magnet to rotate the wipers one step and to close at springs 325 a circuit for placing ground on conductor 360 to energize the left hand winding of the relay 605 as before. The circuit for the magnet 702 of the switch RSA is closed from ground on springs 646, through spring 638 and its break contact, wiper 655 of SQ¹ engaging its second banks contact or a contact multiplied thereto, conductor 577, through the winding of magnet 702 to grounded battery, and a multiple circuit through springs 546, to conductor 383, the latter circuit being open is without effect at this time. Magnet 702 energizes and prepares to advance the wipers 710 and 712, inclusive, of the switch RSA one step, and at spring 709 closes a circuit from ground to conductor 575 to energize the right hand winding of relay 605 as hereinbefore explained. Relay 605 energizes and opens the above traced circuits to end the pulse, the magnet 702 falling to advance its wipers and the magnets 313 falling back preparatory to taking another step. Thus it will be seen that the rotary magnet receives an impulse immediately after the last vertical impulse, the interval between being no longer than the interval between successive vertical impulses. Because of the speed at which the wiper shaft of the finder F¹ is traveling it is necessary that the wipers be spaced two steps off the banks, that is the rotary magnet must receive

two impulses before the wipers engage the first bank contacts. This arrangement is necessary because the wipers in their vertical movement are set to vibrating and if they are 5 cut into the bank level on the first rotary pulse while still vibrating they frequently will not properly engage the contacts of the level. Since the calling line has a finder bank number 25 its bank contacts will appear as the fifth set in the second level, and consequently the rotary magnet must be energized six times to set the wipers on its contacts. The foregoing operation of the rotary magnet and the rotary stepping control 10 magnet continues for five impulses, the relay 605 energizing to terminate each impulse.

Last rotary impulse.

When the magnet 702 deenergizes after the 20 fifth impulse to advance the wiper 710—712 onto their fifth bank contacts, the multiple circuit from the grounded conductor 577 through the springs 546 to the conductor 583 is completed through the wiper 813 of VSA 25 now in engagement with the second contact of its bank over the second B common of group A to the conductor 259, through springs 216 of the line relay, to the conductor 258 which is connected to the fifth C common of the 30 group A, wiper 711 now in engagement with its fifth bank contact, conductor 581, through springs 548, conductor 579, through the second bank contact of SQ¹ through wiper 653 to the winding of magnet 610 to grounded 35 battery, energizing the magnet 610 preparatory to advancing the sequence switch wipers one step with the end of the pulse.

CR¹ switches through.

40 When the relay 605 again energizes to end the impulse, magnets 313, 702 and 610 fall back, the former to performing the same functions as before and the latter advancing the wipers of the sequence switch SQ¹ into 45 their third position. With the sequence switch in the third position the circuits to the magnet, of the finder F¹ and the stepping control switch RSA are no longer closed, and as a consequence, relay 605 remains deenergized long enough to permit the energization 50 of relay 606 over a circuit traceable from ground through springs 644, spring 637 through the upper winding of the relay to battery. Relay 606 upon energizing closes 55 a circuit from ground on spring 645, through spring 640 thence over two parallel branches, the one through the lower winding of relay 601 to battery, and the other over conductor 668, through spring 632 and its break contact, conductor 566, through the winding of 60 magnet 314 of the finder allotter FA¹, to grounded battery, energizing the relay 601 and the magnet 314. Relay 606 also closes 65 a circuit from ground through springs 647, springs 639, springs 641, conductor 652

through springs 625 through the upper winding of relay 602, conductor 568, through the winding of relay 608 to battery, energizing the relay 602 which closes a locking circuit for itself through the relay 601, that circuit 70 being traceable from ground through the upper relay 601, spring 625 and its make contact, through the upper winding of relay 602 thence over the previously traced circuit through relay 608 to battery. It should be 75 noted that the advance of the sequence switch wipers to the third position closes a multiple circuit around the contacts 641 in the circuit just traced for the relay 602, that circuit being closed slightly before relay 606 pulls 80 up, to insure that relay 602 will energize first. The energization of relay 601 operates the springs 623 and 624 to open the circuit of relay 604, that relay being slow to release 85 does not fall back at the instant but remains in its energized position for an interval sufficiently long to permit the completion of the switch through function of the finder F¹ as will be explained presently. The operation of springs 623 and 624 closes a locking circuit 90 for the relay 504 which is traceable from ground through spring 634 and its make contact, conductor 673, spring 624 and its make contact, conductor 566 through springs 543 through the winding of relay 504 and thence 95 over the previously traced circuit through relay 608 to grounded battery. The operation of springs 623 closes a switch through circuit from the ground just traced to spring 624 and its make contact, through spring 623 100 and its make contact, conductor 667, springs 643, conductor 663, through the wiper 351 of FA¹ now in engagement with the first bank contact, through conductor 358, through the winding of relay 306 through resistance 315 105 to grounded battery, energizing the relay 306 to perform functions that will be explained in detail presently. The positioning of the wipers of sequence switch SQ¹ in their third position closes a circuit from ground through spring 646 and its make contact through the third position of the bank of SQ¹, through the wiper 653, through the winding of magnet 610 to grounded battery, energizing the magnet 610 preparatory to advancing the switch 110 wipers to the next bank contact set. The circuit of relay 604 having been opened as explained above, the relay falls back after an interval and closes a circuit from ground through spring 634 and its break contact, conductor 669, through springs 629, conductor 574, through springs 708 and the magnet 702 of RSA to grounded battery, energizing the magnet 702 which interrupts its own circuit at springs 708, and falls back to advance the 115 wipers 710 to 712 of the switch RSA one step. The magnet 702 operates in a buzzer like fashion to advance the wipers until the wiper 712 engaged the contacts 712', at which time 120 a circuit is closed from ground through the 125 130

lower winding of relay 602, through spring 626 and its make contact, conductor 580, through the wiper 712 of RSA, contact 712', conductor 577, through the winding of magnet 702 to grounded battery, holding the magnet energized independent of the contacts 708. Relay 602 is differentially wound and has its lower winding so proportioned that the flux set up therein by the current flowing 10 over the circuit just traced is not sufficient to counteract the flux set up by the current flowing through the upper winding of the relay, consequently the relay remains in an energized position at this time. The de- 15 energization of relay 604 also closes a circuit from ground through spring 634 and its break contact, conductor 669 through springs 628, conductor 560, through springs 810 and the magnet 802 of VSA to grounded battery, 20 energizing that magnet which interrupts to its own circuit at the springs 810 and operates in a buzzer like fashion to advance the wipers 812 to 816, inclusive, forward until the wiper 812 encounters the contact 812'. A circuit is 25 now closed from ground through the lower winding of relay 602, through springs 627, conductor 569 through the wiper 812, through the magnet 802 of VSA to grounded battery, holding the magnet 802 energized independ- 30 ent of the springs 810. The current flowing through the lower winding of relay 602 is thus increased by the amount of current flowing through the magnet 810, and the flux set up in the lower winding by the combined cur- 35 rents of the magnets 802 and 702 is sufficient to counteract the flux set up by the upper winding of the relay, with the result that the relay 602 deenergizes, unlocking the relay 601 permitting that relay to deenergize and 40 thereby restore the control equipment CR¹ to normal in readiness for the next call. Returning now to the deenergization of relay 604, when spring 634 falls back away from its make contact, it removes the ground from conductor 673 through which conductor relay 504 was locked, permitting that relay to deenergize and close the group A start circuit so that if another call should be waiting at the instant, that start circuit will be closed 45 through to relay 501 of the group B control equipment which will handle the call in the manner explained hereinafter. The energization of relay 604 at springs 636 opens the circuit of relay 697 which falls back and at 50 springs 645, 646 and 647 opens the circuit of the sequence switch magnet 610 and the finder allotter magnet 314, permitting those magnets to deenergize and advance their respective wipers to the next contact set.

60 *FA¹ searches for idle finder.*

The deenergization of magnet 314 advances the wipers of the finder FA¹ onto the next bank contact set, for the purpose of illustration it will be assumed that that contact

set is the set leading to the finder F¹, and that at the instant the finder F¹ is busy. A circuit may then be traced from ground on spring 332, the off-normal assembly of the finder F¹ and its make contact, conductor 357, first 70 bank contact and the wiper 352 of FA¹, conductor 671, spring 633 and its break contact, spring 630 and its make contact, conductor 665, through the spring 350, through the winding of the magnet 314 to grounded bat- 75 tery, energizing the magnet, which inter- rupts its own circuit at springs 350, and falls back to advance the wipers one step. If the next finder in the group is busy the bank contact engaged by the wiper 352 will also 80 be grounded and the circuit for magnet 314 will again be completed, that magnet ener- gizing as before to advance the wipers an- other step. In this manner the finder allotter searches for the first idle finder in the group, 85 at which time the above circuit for magnet 314 will not be completed and the finder will come to rest on the contacts leading to that finder.

86 *Operation of finder F¹.*

The operation of the vertical magnet 312 and the rotary magnet 313 of the finder F¹ as explained hereinbefore, positions the wipers 270 to 275 of the finder upon the fifth 95 set of contacts in the second level of the finder banks. It will be noted that the wipers 273 to 275, inclusive, comprising the A group wipers are connected to the break contacts on the relay 307, those wipers being used 100 when the finder F¹ is actuated responsive to the initiation of a call in the A line group. Similarly the wipers 270 to 272, inclusive, comprising the group B wipers are connected to the make contacts through the relay 307, 105 those wipers being used when the finder F¹ is used responsive to the initiation of a call in the group B line as will be explained in de- tail hereinafter. When the vertical magnet energizes responsive to the first impulse it 110 elevates the shaft containing the wiper sets A and B one vertical step operating the off- normal spring ONS, which at springs 331 opens the circuit of relay 603 of the control equipment CR¹ for a purpose which will be 115 explained hereinafter, and at spring 331 and its make contact, prepares a circuit for the release magnet 311, that circuit being held open elsewhere at the time, the release mag- net does not energize. The operation of 120 springs 332 of the off-normal assembly ONS opens a point in the circuit of the wiper switching relay 307, preventing the energi- zation of that relay at this time. When the control equipment CR¹ switches through as 125 explained hereinbefore, and energizes the relay 306, that relay operates springs 327, 328, and 329 to connect the calling line A¹ to the line relay of the selector S¹ over a cir- 130 cuit traceable from ground through the low-

er winding of relay 305 of the selector S^1 , spring 346 and its break contact, conductor 360, springs 329, spring 324 and its break contact, conductor 375, wiper 281, now engaging the plus terminal of contacts sets 125 of the A bank group, through conductor 248, through the hook switch, receiver, transmitter, and calling device of the calling station A' to the negative line conductor 246 to the wiper 279, conductor 273, spring 322 and its break contact, spring 327 and its make contact, conductor 359, through spring 342 and its break contact, through the upper winding of relay 305 to grounded battery, energizing the relay 305. At springs 344, relay 305 closes a circuit from ground on springs 345, spring 334 and its make contact, through the winding of relay 304 to grounded battery. Relay 304 energizes and at springs 335 places ground on the release trunk conductor 358 which traverses the winding of relay 306 to resistance 315 to battery, holding the relay 306 in its energized position. Relay 306 which was energized initially over a circuit under the control make springs on relay 604 must switch through and close the circuit of relay 305 quick enough to permit that relay to energize relay 304 to return the holding ground before the relay 604 of the control equipment CR^1 deenergizes. The energization of relay 306 closes a circuit from ground through spring 333 and its make contact, through spring 328 and its make contact, spring 323 and its break contact, conductor 274, wiper 280 now engaging the private contact of the twenty-fifth bank set of group A, conductor 247 through the winding of relay 203 to grounded battery, energizing the relay 203 which at springs 218 and 219 removes the relay 204 and the ground connection from the conductors of the calling line, leaving that line connected through to the line relay 305 of the selector S^1 with all bridges detached.

45 A dial tone source is interposed between the lower winding of relay 305 and ground in the usual manner. This source is omitted from the drawings to avoid unnecessary complication. The subscriber on hearing this dial tone knows that the central office equipment is in readiness to handle his call. The calling subscriber may then operate the selector S^1 by a manipulation of his calling device CD, to step the wipers 341 to 349, inclusive, to the desired level, from which point the operation of selector S^1 is automatically performed to select an idle trunk in the selected group. The operation of the selector S^1 is well known to those skilled in the art and need not be repeated in detail at this time.

Releasing F^1 .

As the subscriber proceeds with the setting of his call, conductor 358 is extended through springs 343, wiper 348 etc., that con-

ductor being maintained grounded by the release relays of the switches employed, through springs similar to 335. When the conversation is completed and the subscribers have hung up their receivers, ground is removed from conductor 358 in the manner well known to those skilled in the art. Relay 306 which is held energized by ground on conductor 358, deenergizes, and at the normally closed contacts controlled by spring 328, prepares a point in the circuit of release magnet 311. If CR^1 is idle at the moment the circuit of magnet 311 will be closed from ground through spring 333 and its break contact, normally closed contacts controlled by spring 328, spring 331 and its make contact, winding of magnet 311, conductor 664, through springs 348, through the winding of relay 609 to battery. Magnet 311 and relay 609 energize over this circuit, the former to release the switch F^1 and the latter to close the obvious circuit for supervisory lamps 611 and 612. When the shaft of F^1 returns to normal, off normal springs 331 and 332 are moved to their normal positions, the former to open the circuit of 311 and 609 and to reclose a point in the circuit of relay 603. Spring 332 in its normal position closes a point in the circuit of wiper switching relay 307 for a purpose which will be explained in detail hereinafter.

If CR^1 is in use when relay 306 is deenergized, the circuit for magnet 311 and relay 609 will be held open at springs 348 of relay 608. The finder F^1 will not be released until CR^1 restores to normal to permit relay 608 to deenergize.

Line B calling through group B equipment.

Having thus completely traced the circuits involved in a call through equipment of the A group when a group A line is calling I will now proceed with the description of a call from the B group when the call is handled by the group B equipment comprising the finder F^2 and the control equipment CR^2 . When a subscriber at B removes his receiver to initiate a call the line relay 202 energizes over a circuit including springs 213, the calling line, and the instrumentalities at the substation. Assume that at the instant relay 202 energizes, the control equipment CR^2 is idle and in readiness to handle the call. A circuit will then be completed from ground and springs 212 over conductor 256 through springs 513, over conductor 587, through springs 537, conductor 456 through spring 435 and its break contact, conductor 453, through springs 519 through the winding of relay 501, over conductor 550 through the winding of relay 402 to grounded battery, energizing the relay 402 and the relays 501. The former relay opens at its springs 431 a point in the release magnet circuit of the finder F^2 , and the latter registers the finder

number of the calling line in the control equipment CR² preparatory to operating that equipment to connect therewith. The energization of relay 501 at springs 512 closes 5 a circuit for relay 406 traceable from ground through relay 406, through springs 436 and 437 and their respective break contacts in multiple to conductor 458, through springs 512 through the winding of relay 501, locking relay 501, and energizing relay 406 to 10 start the finder control CR² in operation. Relay 501 at springs 511 opens a point in the circuit of register relay 502, to prevent the energization of that relay by the initiation 15 of a call in the A group, and at springs 513, 514, 515, 516 and 517, prepares circuits for controlling the control equipment CR² to step the finder F² on the contacts of the calling line B. The energization of relay 406 20 closes at springs 424 a circuit for the relay 403, which energizes to start the sender of CR² impulsing into the finder.

The first vertical impulse.

25 The energization of relay 403 closes a circuit for the magnet 12 of the finder F², that circuit being traceable from ground through springs 415, spring 420 and its break contact, wiper 431 of the sequence switch SQ² and 30 its first bank contact, conductor 94, wiper 63 of the finder allotter FA² to the winding of vertical magnet 12 of the finder F². At springs 411 relay 406 closes a circuit from ground through springs 411, through springs 35 419 through wiper 438 engaging the first bank contact of the sequence switch SQ² over conductor 467 through the winding of magnet 801 to battery, energizing that magnet. Vertical magnet 12 at armature 43 closes a 40 circuit for the right-hand winding of the stepping control relay 405, that circuit being traced from ground through springs 43 over conductor 83, through spring 531 and its break contact, conductor 460 and hence 45 over two paths in parallel, one to the resistance 412 to battery, and the other through the right hand winding of relay 405 to grounded battery. Magnet 801 upon energizing closes a circuit from ground through 50 springs 804, conductor 470, through two paths in parallel, one to resistance 442 to battery, and the other through the left hand winding of relay 405 to battery. With both of its windings energized relay 405 operates and 55 at springs 419 and 420 opens the circuit thus described for the vertical magnet 12 and the stepping control switch VSB, permitting those magnets to deenergize and allow their armatures to fall back to perform the well 60 known functions. When the armatures 43 and 804 of the vertical magnet and stepping control magnet, both fall back the circuit of relay 405 is opened, permitting that relay to fall back after a brief interval the 65 length of which is determined by the value

of resistances 412 and 442, to again close the vertical magnet circuit. This operation continues as described until the next to the last impulse of the tens digit of the finder back number of the calling line, in this case 70 the calling line is in the twenty-fifth bank position, the last vertical impulse will be the second impulse of the series, at which time the operation is slightly different.

The last vertical impulse.

75 Relay 405 falls back closing the circuit of magnet 12 and 801 as before, it also closes a circuit traceable from ground through springs 511, springs 419, through wiper 438 and its first bank contact, conductor 467, through the springs 516 to the conductor 563, through the tenth A common of group B, through the conductor 255, through springs 211 of the relay 202 to conductor 254, through the second A common of group B through the wiper 809 which engages it, to conductor 551, through springs 514 to conductor 469, through the first bank contact of the sequence switch SQ² engaged 80 by the wiper 440, through the winding of magnet 410 to battery, energizing the magnet 410 of SQ² preparatory to advancing the wipers one step at the end of the impulse. When the vertical magnet 12 and the vertical stepping control magnet 801 have fully energized, relay 405 energizes as before, opening the circuit of those magnets and the circuit just traced for the sequence switch magnet 410, permitting all the magnets to be 85 deenergized. The sequence switch SQ² is thus advanced to its second position preparatory for the next impulse.

The first rotary impulse.

90 When the relay 405 again deenergizes it closes a circuit for the rotary magnet 13 and the motor magnet 701 of the rotary stepping control RSD, over a circuit traceable from ground to springs 416, springs 420 through 95 the wiper 439 of the sequence switch now engaging the second bank contact, over conductor 95, through the wiper 64 of FA² through the winding of the rotary magnet 13 to grounded battery; and the circuit through 100 springs 411, springs 419, wiper 438 now engaging the second bank contact, conductor 468, through the winding of magnet 701 to battery. The rotary magnet energizes and at 105 springs 44 places ground on conductor 83 to close a circuit through the right hand winding of relay 405 as previously explained, and the magnet 701 upon energizing, at springs 704 places ground on the conductor 470 to close a circuit for the left hand winding of the 110 relay 405. With both windings energized the relay 405 again operates to terminate the impulse, permitting the magnets to deenergize and permit their armatures to fall back to perform the usual functions. The de- 115

energization of the rotary magnet and rotary stepping control magnet opens the circuit of the relay 405 which deenergizes to again complete the impulsing circuit. This interaction of the magnets and relay 405 continues as above described until the next to the last rotary pulse. Since the calling line has a blank position 25 its contacts appear in the fifth row of the second level, then the rotary magnet must receive six impulses to reach these contacts since the wipers of the finder F^2 are spaced two steps off the bank, therefore, the foregoing operation takes place for five steps at which time the circuits are closed preparatory to the last rotary impulse.

The last rotary impulse.

Relay 405 falls back closing the rotary magnet circuit as before and closing in addition a circuit for the magnet 410 of the sequence switch, that circuit being traceable from ground to springs 411, spring 419 through wiper 419 and the second bank contact of the sequence switch SQ^2 to conductor 458, through springs 515 to conductor 552, through the wiper 808 of VSB now in engagement with the second bank contact set, over the second B common of the group B to the conductor 253, through springs 210 of the relay 202, to the conductor 252, through the fifth B common of group B engaged by the wiper 705 in its fifth bank position, conductor 554, through springs 517, through conductor 466, through the second bank contact and wiper 440 of SQ^2 , through the winding of magnet 410 to grounded battery, energizing the magnet preparatory to advancing the wipers of the sequence switch at the end of the impulse. When the relay 405 again energizes to terminate the impulse, the sequence switch SQ^2 advances to the third position in which the control equipment CR^2 is in position to switch through.

CR^2 switches through.

With the sequence switch SQ^2 in its third position, the circuits to the finder magnet and stepping controls are open with the relay 405 again deenergizes, completing the circuit for slow operating relay 404 which energizes after an interval, and at springs 406 closes a circuit from ground through springs 414 and 416, conductor 471, through the lower winding of relay 409 to grounded battery, energizing that relay. Relay 404 also completes a circuit from ground to springs 415, springs 417, conductor 473, through spring 429 and its break contact, through the upper winding of relay 408, over conductor 450 through the winding of relay 402 to grounded battery, energizing the relay 408 which locks itself over a circuit from ground to the upper winding of relay 409, through springs 429 and its make contact, through the upper winding of relay 408, 65 thence over the previously traced circuit

through the relay 402. Relay 404 also closes a circuit from ground to springs 414, springs 416, conductor 471, spring 427 and its break contact, conductor 89, through the magnet 14 of the finder allotter FA^2 to grounded battery 70 energizing that magnet preparatory to advancing the wipers of the finder allotter onto the next set of bank contacts. Relay 409 upon energizing closes a circuit from ground through springs 422 and its make contact, springs 437 and its make contact, springs 436 and its make contact, spring 412, conductor 92 through the wiper 61 of the finder allotter FA^2 , conductor 73, conductor 68 through the winding of the relay 6, through resistance 15 80 to grounded battery, energizing the relay 6 to switch the finder through in a manner which will be subsequently explained. The operation of relay 409 opens a circuit of relay 406 which was closed through the springs 436 and 85 437 and their respective break contacts, but relay 406 being slow to release does not deenergize immediately but remains in its energized position long enough to permit certain other switch through functions to be performed. The operation of relay 409 closes a circuit from ground through springs 422, spring 437 and its make contact, conductor 458, through spring 512 and its make contact, through the winding of relay 501, over 90 conductor 450, through relay 402 to grounded battery, locking the relay 501 in its energized position to prevent the closure of the start circuit until the control equipment CR^2 is in position to handle another call. The energization of relay 408 prepares a point in the restoring circuit of the magnet 701 and 801 of the rotary stepping control RSB and the vertical stepping control VSB, respectively, that circuit being completed when the relay 406 100 deenergizes a moment later, closing at spring 422 and its break contact, a circuit from ground over conductor 472, through spring 432 and its make contact, conductor 463, through interrupter springs 803 and through 110 the winding of the magnet 801 of the switch VSB to grounded battery, energizing that magnet which interrupts its own circuit at springs 803 and falls back to advance its wipers. When the magnet falls back it again 115 closes its own circuit and reenergizes. This buzzer like action continuing until the wipers are in engagement with the contact 805'. Similarly the deenergization of relay 406 closes a circuit from springs 422 and its break 120 contact, conductor 472, through springs 433 and its make contact, conductor 464, through interrupter springs 703 and magnet 701 of the switch RSB to grounded battery, energizing that magnet which interrupts its own circuit at springs 703 to operate in a buzzer like fashion to advance the wipers of the switch RSB to the normal position, the operation continuing until the wiper 707 engages the contacts 707'. When the switch RSB 130

and VSB have reached the next to normal position in which the contacts 707' and 805' are encountered, the circuit is closed from ground to the lower winding of relay 408, 5 through to spring 430 and its make contact, over conductor 465, to wiper 707 engaging the contact 707', conductor 468 through the winding of magnet 701 to grounded battery, holding the magnet 701 energized independent 10 of the circuit through its interrupter springs 703. A second circuit is closed from ground through the lower winding of relay 408, springs 431, conductor 461, wiper 805 engaging contact 805', conductor 467, through the 15 winding of magnet 801 to grounded battery holding the magnet 801 energized independent of its interrupter contacts 803. Relay 408 is differentially wound, the lower winding being so proportioned that when the magnets 20 801 and 701 are both energized through it, the flux produced by that winding is of sufficient strength to overcome the flux produced by the upper winding and the relay deenergizes. The deenergization of relay 408 unlocks the circuit 25 for switching relay 409 permitting that relay to be deenergized to restore the start circuit to their normal condition. Relay 408 opens the circuit of the magnet 701 and 801, permitting those magnets to deenergize to advance 30 the wipers one more step into the normal position. The deenergization of relay 406 opens at springs 424 the circuit of relay 403, which falls back and opens the circuit for the magnet 410 of the sequence switch SQ², to advance 35 the wipers of that switch one step, positioning them on contacts multiplied to the first bank set, from which position they are to control the circuits of the vertical magnet of the allotted finder. The deenergization of relay 403 also opens a circuit of the finder allotter 40 also magnet 14, permitting that switch to advance the wipers 61 to 65, inclusive, to the next bank contact set, selecting the next finder and connecting it with the control equipment CR², if the next finder is idle at the time. The deenergization of relay 406 also opens the locking circuit previously traced with the relay 501, permitting that relay to fall back and transfer the start circuit from group B to 50 group A, so that if a call was initiated in group B before the relay 409 deenergizes, that call will be handled by the group A equipment in a manner which will be explained in detail hereinafter. The control equipment 55 is now restored to normal in readiness for the next call.

FA² searches for idle finder.

When the magnet 14 of the finder allotter 60 FA² deenergizes as explained above, and advanced its wipers onto the next bank contact set, it seizes that finder and associated it with the control equipment CR² if the finder is idle, but if the finder is busy the finder allotter continues to the next contact set. The magnet 14 is reenergized over a circuit traceable from ground, off normal spring 40 and its make contact finder F², conductor 69, through wiper 65 of FA², conductor 96, spring 421 and its break contact, spring 426 and its make contact, conductor 90, through interrupter springs 60, through the winding of magnet 14 to grounded battery. The magnet energizes and interrupts its own circuit at interrupter 70 springs 60 to advance the wipers to the next contact set. If the contact set is busy the magnet circuit will again be closed and interrupted, the switch is operating in a buzzer like fashion until the first idle finder is reached, at which time the circuit of magnet 75 80 14 will not be closed and the wipers will come to rest on that contact set.

Operation of finder F².

As indicated, the vertical magnet 12 carries 85 the wiper sets A and B of the F² in a vertical direction, the first energization of relay 12 operating the off normal springs ONS, placing ground upon the conductor 69, through spring 40 and its make contact, to mark the 90 finder engaged, spring 41 and its make contact preparing a point in the circuit of the release magnet 11, that circuit being held open elsewhere at this time to prevent the 95 operation of the magnet. Since the call now being described comes from the group B equipment it is necessary that the wiper switching relay 7 be energized to connect the 100 finder with the group B wipers comprising 76 to 78, inclusive, that being accomplished over a circuit traceable from ground over springs 510 of the relay 501, conductor 452, 105 springs 421 and its make contact, conductor 96, wiper 65 of FA², conductor 69, off-normal spring 40 and its break contact, through the 110 winding of relay 7 to grounded battery, energizing that relay which locks itself after the first vertical step of the switch over a circuit from ground on springs 40 and its make contact, conductor 69, spring 50 and its make 115 contact through the winding of relay 7 to grounded battery. In order that the relay 7 which is initially energized through spring 40 and its break contact, and subsequently locked through spring 40 and its make contact, may remain in its energized position, the break contact of the off-normal spring is adjusted with considerable follow so that the combination is essentially a make-before-break combination, that is spring 40 engages 120 its make contact before it breaks away from its break contact. When the calling line B is making a call, vertical magnet 12 is operated twice to elevate the group B wipers opposite the second level of the upper set of 125 banks of the switch, and then rotated by magnet 13 six steps, the wipers coming to rest on the fifth bank contact in the set, after which the finder is switched through by the 130 energization of relay 6 as explained above.

Relay 6 upon energizing closes a circuit from the calling station over wipers 76 and 78, through springs 51 and 53 and their respective make contacts, springs 46 and 48 and 5 their respective make contacts, through the windings of line relay 5 of the selector S², energizing that relay which closes a circuit for the release relay 4, which energizes and places ground on conductor 68 through the 10 spring 31 and its make contact, that ground feeding back to hold the relay 6 in its energized position after its initial circuit was broken by the deenergization of relay 406 and the control equipment CR². The energization of switch through relay 6 also closes a circuit from ground to springs 42 and its make contact, spring 47 and its make contact, 15 spring 52 and its make contact, release conductor 77 and release wiper 231 now engaging the contacts connected with bank multiple wire 241, through the winding of relay 201 to grounded battery, energizing that relay to open the circuit of relay 202 which was traced through springs 215 and 214, leaving 20 the calling line connected to the selected switch S², without any attachments either in the line equipment or in the finder. Dial tone will be transmitted to the calling substation in the usual manner. The subscriber may 25 then operate the selector B in the well known manner to extend the connection in the direction of the desired called line, that operation being familiar to those skilled in the art and will not be repeated here.

35

F² releases.

Finder F² is held energized throughout the extension of the connection and during the conversation period, by a ground sent 40 back to it over conductor 68. When the call is completed and the subscribers have hung up their receivers, this ground is removed. Relay 6, which was held in its energized position by this ground deenergizes and closes 45 a circuit for the release magnet 11, traceable from grounded spring 42 and its break contact, normally closed contacts controlled by spring 47, ONS 41 and its make contact, winding of magnet 11, conductor 72, springs 50 441, winding of relay 401 to battery. Magnet 11 and relay 401 energize over this circuit, the former to release F² to normal and the latter to light supervisory lamp 480. When the shaft of F² reaches its normal position, ONS operates, spring 41 opening the 55 circuit of 11 and 401 and closing the circuit of 407 and 42 preparing a point in the circuit of relay 7. If CR² is busy at the time relay 6 deenergizes, the release magnet will be open 60 at springs 441 until relay 402 deenergizes.

Having thus completed the description of the operation of the system of my invention when it is functioning in a normal manner, I will now proceed with a description of its operation when an unusual condition is placed

upon it. That condition may be due either to faulty equipment or to unusual traffic conditions which impose an extra heavy load upon the finders, requiring special facilities for handling.

70

All group A finders busy.

If conditions are such that an unusually large number of group A subscribers are calling, it may easily occur that all the finders in group A may be busy at an instant, and if special provisions were not made to handle additional calls, other subscribers in the group would be without service at the time. For the purpose of handling the situation such as this I have provided an all finder busy relay 603 in the control equipment CR¹, that relay being permanently energized over a circuit traceable from ground on springs 333 and its make contact, of the finder F¹, normally closed contacts controlled by springs 328, off-normal spring 331 and its break contact, conductor 262, through spring 532 of the key K and its break contact, conductor 567, through the winding of relay 603 to grounded battery. Conductor 262 is multiplied to all of the finders in group A, and as long as one of these finders remain in its normal position the circuit of relay 603 will be maintained and that relay will remain in its energized position. When the last finder of the group is taken for use and moved off-normal the relay 603 is no longer energized, except for an auxiliary circuit closed through springs 635 under the control of the start relay 604 of the control equipment CR¹, therefore, when the control equipment CR¹ restores to normal, relay 603 deenergizes, closes a circuit from ground through springs 632 and its break contact, conductor 668 through the lower winding of relay 601 to grounded battery, energizing that relay to transfer the start wire circuit of the group A line from the group A register relay to the group B register relay, so that in the event a call is originated in the group A line, the start circuit will be closed as follows: As soon as relay 206 is energized to start a call, ground will be placed on the start wire by spring 222, this circuit going over conductor 257, through springs 544 and its break contact, conductor 585, spring 520 and its break contact, conductor 562 through springs 621 and its make contact, conductor 455, through springs 434 and its break contact, conductor 454, through springs 511, through the winding of relay 502, conductor 455, to springs 454 and its break contact, springs 511 through the winding of relay 502, conductor 450 through the winding of relay 402 to grounded battery, energizing the register relay 502 which straps the banks of the group B sender switches RSB and VSB in accordance with the finder bank designation of the group A line which is calling, so that those switches

control the finder through wipers 806 and 807 and 706 to position the group B finder F^2 on the contacts leading to the calling line A^2 . Returning now to the operation of the 5 control equipment CR^1 when the all finder busy relay 603 deenergizes, will be noted that the circuit from the test wiper 352 of the finder allotter FA^1 to the interrupter springs 350 and the motor magnet 314 of the finder 10 allotter FA^1 is led through springs 630 and its make contact, that circuit being open by the springs 630 when the all finders busy relay 603 deenergizes. This arrangement prevents an unnecessary rotation of the finder 15 allotter FA^1 , since all finders of the A group are busy, that switch will be unable to stop on any contact sets, and would rotate continuously if the above provision to stop it was not provided. When all finders busy condition 20 at the finders of group A has passed, one of the finders restores to normal, relay 603 again energizes and opens the circuit of relay 601 permitting that relay to deenergize to transfer the start circuit, so that a call 25 originating in the A group of lines will be effective to start the A group control equipment CR^1 to direct an idle finder to the contacts of the calling line. As soon as springs 630 again closes a circuit through its make 30 contact, the finder allotter FA^1 if it is standing on the contacts of a finder other than the idle one, will rotate until the idle finder is found and the system is again back to its 35 normal condition.

35   *All group B finders busy.*

The control group CR^2 controlling the B group of finders has also been provided with an all finders busy relay 407 which is constantly 40 energized over a circuit from ground over springs 42 and its make contact, normally closed contacts controlled by springs 47, off-normal springs 41 and its make contact, conductor 82, springs 527 and its break contact, conductor 459 through the winding of relay 407 to grounded battery. The conductor 82 is multiplied to all of the finders in the groups and when the last finder moves off normal, the relay 407 is held energized 45 through the make springs 423 on relay 406 of the control equipment CR^2 . When that relay deenergizes, closes a circuit for switching relay 409 traceable from ground through springs 427 and its make contact, conductor 471, through the lower winding of relay 409 to grounded battery. Relay 409 energizes and switches the circuit of the group B start conductor, so that in the case a call is originated 50 in the group B line, it will be effective to start the group A control equipment to send a group A finder after the call. The above circuit is traceable from ground, springs 212, conductor 256, break contacts 413, conductor 587, through break contacts 537, conductor

456, through spring 435 and its make contact, 65 conductor 457, through springs 622, conductor 565, through springs 452, through the winding of relay 503, conductor 568, through the winding of relay 608 to grounded battery. Relay 503 energizes to set up the number of 70 a group B calling line in the group A equipment. The energization of relay 503 prepares a circuit which is closed by the subsequent energization of relay 604, through the wiper switching relay 307 of the finder F^1 , 75 that circuit being traceable from ground on springs 549, conductor 561, spring 633 and its make contact, conductor 671, wiper 352, conductor 357, off-normal springs 332, through the winding of relay 307 to battery. Relay 80 307 energizes over this circuit and disconnects the group A wipers of the finder F^1 and connects in their place the group B wipers so that when the finder is subsequently positioned on the bank contacts, connection will 85 be made to the group B line. The deenergization of relay 407 with the control equipment CR^2 opens at springs 426 the circuit for magnet 14 of the finder allotter FA^2 preventing that magnet from rotating either 90 switch. When one of the finders of the B group become idle a circuit is again established for the relay 407, which energizes, opening the circuit of relay 409 which deenergizes to switch the circuit back to its normal condition. Relay 407 reestablishes the 95 circuits which it has just broken, and the equipment is once more in its normal position.

100   *The group A fuse blows.*

In Fig. 6 I have shown a plurality of battery connections connected directly to the various relays and magnets, in order to simplify the drawings as much as possible. In an installation such as I have shown the control equipment CR^1 , sequence switch SQ^1 , vertical stepping switch VSA and rotary stepping switch RSA , finder allotter FA^1 , would be fused through one common fuse, with the exception of the switching relay 601 which 105 is fused through a separate fuse. In the event if the main fuse blows 603 would be deprived of its energizing current and would fall back closing a circuit for relay 601 which 110 would pull up to switch the start circuits over 115 to the group B equipment, relay 603 upon deenergizing closing and opening the other circuits it controls as in the case of an all finder busy condition. Under these circumstances the control equipment CR^2 of the 120 group B can control the finders of group B responsive to calls from either groups A or B. The main fuse of the control equipment CR^1 is provided with the usual and well known signal to inform the attendant of the 125 station when the fuse blows, and after he has replaced it relay 603 will again energize opening the circuit of switching relay 601

which will deenergize to return the group A start circuits to normal to control the group A equipment CR¹.

Group B fuse blows.

- 5 Similarly the control equipment CR² is fused in common through a main fuse, and switching relay 409 is fused separately as shown. When this main fuse blows relay 10 407 deenergizes closing a circuit through relay 409 which energizes to switch the group B start circuit through to the group A control equipment. When the fuse is replaced relay 15 407 reenergizes, opening the circuit of relay 409 which deenergizes returning the equipment CR² to normal, so that calls from the group B line are handled by the group B equipment in the usual manner.

20 *Fault alarm.*

- Control equipment CR¹ is protected against a tie-up by means of a slow alarm set, which is controlled through springs 649 of relay 608 in multiple with the supervisory lamp 613. 25 When the relay 608 is energized at the time the equipment CR¹ is taken into use, lamp 613 is lighted immediately to designate that the equipment is occupied. A circuit is also closed to springs 649 through a slow alarm set, which may be of any well known type, and which actuates after a definite interval to bring up a fault alarm, which indicates that the equipment is being occupied longer than is necessary for the successful completion of its functions. In the foregoing detailed description of the operation of CR¹ it was pointed out that the relay 602 which energizes at the beginning of the switch-through operation locks itself to the upper winding of relay 601 and through relay 608 to battery. 30 Relay 602 is the return to normal control relay, and is differentially wound, its second winding being energized in series with the motor magnets of the vertical stepping control VSA and the rotary stepping control RSA to deenergize the relay. When some electrical or mechanical fault prevents the stepping switches from returning to their normal positions, the lower winding of relay 40 602 will not be energized, and consequently the relay will not deenergize and relay 608 will be held up long enough for the slow alarm device to actuate and bring up its signal. The attendant upon seeing this signal 45 knows that a control equipment is tied up, and upon noting the lighted lamp 613 he knows the switch control equipment is tied up.

The equipment CR² is similarly provided with a fault alarm, actuated by a slow alarm set individual to the latter equipment. This alarm is under the control of relay 402 which is energized by the locking circuit of differential relay 408 over the circuit which has been previously traced. When a fault de-

velops in the equipment CR² which prevents stepping control switches from returning to their normal position the slow alarm set will actuate the fault alarm to apprise the attendant that the equipment is tied up. A supervisory lamp similar to lamp 613 is provided with equipment CR² to inform the attendant which equipment is tied up. The supervisory lamp of CR² is not shown on the drawings, as its circuit arrangement is in exact duplicate of that of lamp 613, it is thought that its operation will be readily understood and that the drawings would be needlessly complicated by its inclusion.

SIMULTANEOUS CALLS.

Two calls in group A, no calls in group B.

In the event that two lines in group A initiate calls simultaneously, the group A equipment will be operated to connect with the line having the lower sender bank number first, that is, if lines 115 and 125 call simultaneously, the finder will connect with line 115 first. The energization of relay 206 of the line 115 to start the call closes the A start circuit traceable from ground through spring 222, conductor 257, springs 544, conductor 585, springs 520, conductor 552, spring 621 and its break contact, conductor 563, springs 536, through the winding of relay 504, conductor 568, through the winding of relay 608 to grounded battery, energizing relay 504 which locks itself through springs 543, conductor 566, springs 623, the winding of relay 604 to ground. Relay 504 upon energizing, at 50 springs 544 opens the A start circuit from the equipment, so that ground placed on the common start conductor 257 by other calling lines in the group, has no effect at this time. Control equipment CR¹ functions to position the finder F¹ on the contacts of the calling line of the lowest finder bank position, that is, with relay 206 energized, a circuit for magnet 610 of SQ¹ will be closed over a circuit traceable from ground through springs 646, springs 638, wiper 655 of the sequence switch SQ¹ in position 1, conductor 578, springs 547, conductor 582, the tenth A common of group A, conductor 260, through springs 220 of the relay 206, conductor 282, to the first A common of group A, wiper 814, engaging that common, conductor 584, springs 545, conductor 576, wiper 653 of SQ¹, through the magnet 610 to grounded battery. The finder having been positioned vertically, a number of steps corresponding the designation of the line A², can complete only one rotary circuit, that being the circuit of calling lines in the level marked by the position of the vertical stepping switch VSA as is explained in detail elsewhere. The operation of the finder F¹ and the equipment CR¹ in connecting to the bank contacts of the calling line, as explained in detail hereinbefore is repeated without regard to the

simultaneous call condition until the switching relay 601 is energized. Relay 601, opens the circuit of relay 604 at springs 623, and opens the locking circuit of relay 504 at the same point. Relay 504 being quick acting falls back immediately and at springs 544 closes the A start circuit, and the equipment is arranged to handle the second call in the A group. Relay 204 being energized will place ground on the start conductor 257 at springs 217, closing the circuit through springs 544, springs 520, conductor 562, spring 621 and its make contact, the relay 601 still being in its energized position, conductor 455, springs 434 and its break contact, conductor 454, springs 511 and its break contact, through the winding of relay 502 over conductor 450, through the winding of relay 402 to grounded battery. Relay 502 energizes and at springs 518 closes a locking circuit for itself traceable over conductor 458 through springs 436 through the winding of relay 406 to ground. The energization of relay 502 registers the finder bank designation of the second calling line A¹ in the group B equipment, that equipment functioning in the above explained manner to position the finder F² into connection with the calling line. It will be noted that the A start circuit is held open until the control equipment handling the first of the two simultaneous calls is advanced to the switch through position, at which time the second call is picked up by the group B equipment, if there are no group B calls in progress at the instant.

Two calls in group B no calls in group A.

Similarly in the event of two simultaneous calls in group B, the start conductor 256 is grounded at spring 212 of the relay 202 of one of the calling lines, closing a circuit over that conductor through spring 513 and its break contact, conductor 587, springs 537, conductor 456, spring 435 and its break contact, conductor 453, springs 519 through the winding of relay 501, conductor 450 through the winding of relay 402 to grounded battery. Relay 501 energizes to register the finder bank designation of the calling line in the group B control equipment. Relay 501 at springs 512 locks itself over conductor 558, springs 436 at the winding of relay 406 to ground, and at springs 513 opens a point in the B start circuit. When the control equipment CR² reaches its switch through position, relay 409 is energized and at spring 435 switches the start circuit from relay 501 to relay 503. The energization of relay 409 at springs 436 unlocks the relay 501, which deenergizes immediately and closes the start circuit from ground placed on conductor 256 by the second call, springs 513, springs 537, spring 435 and its make contact, conductor 457, springs 622, conductor 565, springs 542 through the winding of relay 503, conductor 568, through the winding of relay 608 to grounded battery. Relay 503 energizes to register the designation of the B calling line in the A control equipment. Relay 503 at springs 537 opens a point in the B start conductor to prevent the starting of any further calls at the instant. Relay 503 locks itself through springs 535, conductor 566, springs 623, winding of relay 604 to ground, that locking circuit being opened at springs 623 when the control equipment CR¹ moves to the switch-through position and energizes the relay 601.

Two simultaneous calls group A with a call in group B.

A line in group A and a line in group B may call simultaneously without interference with each other if their respective control equipments are idle at the instant. The A group line energizing relay 504 to start the finder equipment and the B group line energizing relay 501 to start its finder equipment. If a second line in the group A calls simultaneously with the first line, at the same time that a call is being put through in the group B equipment, the second call will be handled by whichever control equipment restores to its normal position first. As has been explained relay 504 holds the A start circuit open at springs 544, assuming that the control equipment CR¹ reaches the switch-through position, relay 601 is energized, and unlocks the start circuit relay 504 which at springs 621 transfers the A start circuit to the relay 502. However if relay 501 is still energized at the time, the circuit of relay 502 is held open at springs 511, therefore the second call in the group A cannot be handled by the already busy group B equipment, but must wait. When the group B equipment reaches its switch-through position, relay 409 energizes opening another point in the circuit of relay 502 at springs 434, relay 501 being unlocked falls back and closes springs 511 immediately. The second call in group A is now ready to seize whichever control equipment restores to normal first. Relay 504 is in its normal position, but the A start circuit is not closed to this relay until the control equipment CR¹ reaches its normal position and relay 601 restores. Similarly, relay 501 is back, having completed its function in connection with the setting of the calling group B equipment, but the A start circuit is held open from the group B control equipment until the switching relay 409, therein, is restored to normal responsive to the restoration to normal of the control equipment CR². As soon as one or the other of the control equipment reaches its normal position, its respective switching relay will be deenergized, closing the corresponding circuit in the A start conductor to the idle control equipment. The circuit of

the second simultaneous call will be immediately picked up either by relay 504 or 502, and the call will thus be handled.

5 *Operation of key K.*

In the foregoing description of the control equipments CR¹ and CR² are cut out of service under conditions which were only momentary. That is, the blowing of a fuse 10 brings in the alarm immediately and the attendant can replace the damage in a few minutes, and in a correctly designed system an all finders busy condition does not exist for a very long period of time. However, 15 it may happen that some trouble will develop in the control equipments which will require that they be removed from service for a relatively long period of time. For example a 20 relay coil may burn out, or a pawl on one of the sequence switches might break, in which case a relatively long period of time will be required to repair the damage. Under these 25 circumstances the key K is operated to divert the calls from both line groups to the remaining group of control equipment, and to throw the two groups of finders together as one large group under control of that single 30 equipment. After operating the key K as required, the attendant can repair and adjust 35 the control equipment which he has cut out of service without in any way affecting the traffic of the exchange.

Key K in position 1.

35 Assuming that a case of trouble develops in the control equipment CR² and that the attendant deems it necessary to cut that equipment out and repair it, he will operate the key K into the position 1, to arrange the 40 circuits so the control equipment CR¹ will handle calls from both the A and B groups of lines. The operation of the key K in position 45 1, groups the A and B groups of finders into one large group under the control of the control equipment CR¹.

It will be noted that I have divided the 50 banks of the finder allotter FA¹ into two halves, the upper half of the banks being labelled group A and containing trunk conductors leading to the finders of group A of which finder F¹ is a sample. The lower half of the banks are labelled group B and terminate trunk conductors leading to the finders of group B of which finder F² is an example. Normally finder FA¹ has no access 55 to the group B finders because the test wiper 352 encounters a grounded contact while the wipers are in engagement with trunk contacts leading to the B group. Similarly, the finder FA² has its banks divided into two sections, 60 the upper section being labelled group B and containing the contact terminating trunks leading to finders of the B group of which F² is a sample, and the lower half of the banks 65 contain trunks from the finders of group A.

The key K is operated as described, and ground is removed from the B half of the banks of the finder allotter FA¹ to permit that allotter to connect with finders in the B group. The circuit open is the one from 70 ground on springs 550, conductor 451 to the contacts of the bank over which wipers 352 rotate. The operation of springs 525 throw a shunt on the springs 520 of the relay 502, to prevent the opening of the A start circuit in the event that relay 502 becomes energized while the attendant is working on the control equipment CR². Spring 526 throws a similar shunt around the springs 513 of the relay 501, to prevent the B start circuit from 75 being opened should the relay 501 become energized. The operation of springs 527 opens the circuit of all finders busy relay 407 of the control group CR² that circuit originating in the finders of the B group which 80 collectively places ground on conductor 82. Relay 407 thereupon falls back closing a circuit at springs 427 for switching relay 409, which energizes and switches the B start circuit from 85 the relay 501 which is normally connected, 90 to the relay 503 so that calls originated in the B group would be set up in the A group control equipment. The operation of springs 530 connects the auxiliary test wipers 355 of 95 the finder allotter FA¹ to the magnet of FA¹ through the interrupter springs 350, so that that wiper may control the magnet to position the finder allotter wipers on trunks leading 100 to an idle finder in the B group. The operation of springs 531 disconnects the reversible pulse control wire 83 from the circuit of relay 405 of the control equipment CR² and connects it instead to the relay 605 of the control equipment CR¹, so that the magnets 105 of the finders in the group B may be controlled by the interrupter mechanism of the group A control equipment.

Finder F² controlled by CR¹.

With the key K thrown in the number one 110 position and the circuits established as above enumerated, the operation of the equipment in response to calls from the A group is exactly as has been described hereinbefore, and need not be repeated at this time. However 115 the operation of the equipment when a call originates in the B group is somewhat different and will be explained briefly. The B start circuit which is normally connected to the start relay 501 of the equipment CR² is now connected through spring 435 and its make contact, through the relay 503, the circuits traversing springs 622 and springs 542. If a call in the A group is in progress, relay 120 504 will be energized, and the B start circuit will be maintained open by spring 622 when the equipment CR¹ reaches the switch-position and the call from the B group will therefore be delayed until the A group connection 125 has been established. Otherwise the opera- 130

tion of the system in connection with calls in the B group is the same provided that there is an idle finder in the A group. When the finder allotter FA¹ has connected with and operated the last finder in the A group, the magnet 314 is operated to advance the wipers 351 and 355 so that the wiper 355 connects on the contact to which conductor 69 is connected. Test wiper 352 through which the 5 finder allotter seeks idle finders in the A group, strikes an open circuit because ground has been removed from the B half of the bank over which that wiper rotates by the operation of springs 550 to remove ground to conductor 451. With the wipers so positioned, 10 finder allotter is associated with the first finder of the B group, assumed to be the finder F² and if that finder is idle at the time FA¹ will not be energized and the finder F² will not be controlled by the control equipment CR¹. CR¹ will be operated responsive to the initiation of a call, and will send the vertical pulse out over the vertical impulsing circuit including wiper 353 of the finder 15 allotter FA¹, now engaging conductor 74 which is connected from pin 74² to pin 74¹, by a conductor not shown, thence through the winding of the vertical magnet 12 to the finder F² to operate that magnet in the well 20 known manner. The magnet on operating closes springs 43 which sends the ground back over conductor 83, through spring 531 and its make contact, conductor 564, and hence over two parallel paths through resistance 25 614 to battery, and through the left-hand winding of relay 605 to battery. Relay 605 energizing when its right-hand winding is energized by revertive pulse received from the switch VSA as explained hereinbefore. 30 At the end of the vertical pulse the sequence switch SQ¹ steps to the second position and the rotary pulses are sent out over a circuit including wiper 354, conductor 75 which is connected from pin 75² to pin 75¹, by a conductor not shown to the winding of rotary 35 magnet 13 to grounded battery. Magnet 13 energizes, again grounding the revertive pulse conductor 83 to energize the left-hand winding of relay 605 preparatory to operating that relay to end the pulse. When the 40 last rotary impulse has been sent and the sequence switch moves to position 3, relay 606 energizes and at springs 640 closes a circuit of switching relay 601, which closes the 45 finder switch-through circuit which includes wiper 351 of the finder allotter FA¹, conductor 87, conductor 73, conductor 68 through the winding of relay 6, through resistance 15 to grounded battery, energizing that relay to switch through the finder F² in the hereinbefore explained manner. At the end of the switch-through operation the allotter magnet 314 is energized and advances the wipers onto the next bank contact sets. When 50 this contact set is busy, ground will be

present thereon over a circuit traceable from grounded conductor 69 of the finder such as F², that conductor being connected to wiper 355 of the allotter FA¹, conductor 559, through springs 530, conductor 560, through 55 springs 633, springs 630, conductor 665, interrupter springs 350, through the winding of the magnet 314 to grounded battery, over which circuit the allotter FA¹ performs the usual hunting operation, bringing its wipers to rest on the banks of the first idle finder encountered. All finders busy relay 603 of the equipment CR¹ is now held energized over two circuits, the one from the springs 633, of the finder F¹, that circuit having been traced in detail previously, and the other from the spring 42 of the finder F² over a circuit from ground on springs 42, normally closed contacts controlled by spring 47, spring 41 and its break contact, conductor 82, 60 through spring 527 and its make contact, conductor 567 through the winding of the relay 603 to battery. In the event of an all finders' busy condition in group A, relay 603 will still remain energized if there are some 65 idle finders in group B. In the event of a simultaneous all finders busy condition in group B, relay 603 will deenergize, opening the circuit of the magnet of allotter FA¹, at springs 630 to prevent needless rotation of that switch, and momentarily throwing the groups A and B out of service. However, with the two finder groups as one sufficient finder are available for the 200 lines, and it would only be under unusual conditions that 70 all finders of both groups would be busy. 75

Key K in position 2.

Similarly the operation of key K to position w, removes the equipment CR¹ from service and groups all the finders into one large group under the control of equipment CR². The operation of the key K operates the springs 551 to remove ground from the A half of the banks of the finder allotter FA², so that allotter may have access to finders of the A groups, springs 534 shunt the springs 544 to prevent opening the A start circuit by the operation of relay 504. The operation of spring 533 shunts springs 537 to prevent the 80 opening of the B start circuit by the operation of relay 503. The operation of spring 532 opens the circuit of all finders busy relay 603 of CR¹ permitting that relay to fall back to perform its usual function, springs 532 also closes an auxiliary circuit for the all finders busy relay 407 of CR², so that finders of group A jointly control the operation of that relay. The operation of springs 529 connects the wiper 62 of allotter FA² through the magnet 14 through interrupter springs 60, so that that wiper may be employed as a test wiper to search over the A group when the allotter is looking for an idle finder. The 85 operation of spring 528 opens the revertive 90

120

125

130

135

control pulse circuit, from the senders such as F^1 , which is normally terminated in the left-hand winding of relay 605 of equipment CR^1 , and closes that circuit through to the right-hand winding of the relay 405 of equipment CR^2 so that the finder F^1 may send back its revertive pulse to control the interrupter when CR^2 is directing the operation of the finder F^1 . The operation of the system of the key in position 2 is the same as it was with the key in position 1 except that CR^2 is controlling all of the finders instead of CR^1 . It is thought that a detailed description of this operation is not necessary at this time as it will be apparent from the preceding detailed description.

Connector calls A^2 before finder connects to it.

It will be apparent from the foregoing description of the operation of the system that the calling line such as A^2 , is not protected in the banks of the connector until the finder connects to it and switches through, that is, the private conductor of the calling line is not grounded until the switching relay of the finder pulls up. It may happen that after the calling subscriber initiates a call and before the finder has connected with the calling line, the connector may connect to it, in which case the connector is given the right away and the finder equipment is restored to normal. Assuming that the station A^2 has initiated a call, energizing relay 203 to start the control equipment CR^1 to direct finder F^1 to the terminals of that line, and that before the vertical impulsing has commenced the connector serving that line connects to the normal conductors connected to conductors 249 and 251, inclusive. The connector will immediately switch through and energize the relay 205, which opens the circuit of the relay 206 permitting that relay to fall back and move the calling line designation from the banks of the vertical stepping switch VSA and the switch RSA. With the vertical magnet of the finder functioning normally the sender will continue to send pulses to it, stepping the wipers up to the ninth level, and simultaneously stepping the switch DSA around until its wiper 814 encounters the ninth bank contact, at which time the sequence switch SQ^1 is energized over a circuit from ground to springs 646, springs 638, wiper 655 including the first bank contact, conductor 578 to springs 547, conductor 583, through the tenth A common of group A now engaging wiper 814 through that wiper through conductor 584 to springs 545, conductor 576, through the first bank contact position, wiper 653 of sequence switch SQ^1 through the winding of magnet 610 to grounded battery, energizing the magnet in multiple with the magnet of VSA and the magnet 312. When the relay 605 terminates the pulse sequence switch advances to the tenth rotary position

and impulses are diverted to the rotary magnet 313 of the finder F^1 and the magnet 702 of the switch RSA. Since there are no finder bank numbers set up in the banks of the switch RSA ten impulses will be delivered thereto, to position the wiper 710 in engagement with the tenth C common of group A. The positioning of wiper 711 closes a circuit for the sequence switch motor magnet so that when the eleventh rotary impulse sent to position the finder switch wipers on the tenth bank contact, the circuit is also closed from ground to springs 646, springs 638, wiper 655 now engaging the second bank contact, conductor 577, springs 546, connector 533, through the tenth C common of group A, wiper 711, through conductor 581, springs 548, conductor 579 through the second bank contact of wiper 653 through the winding of the magnet 610 to grounded battery, energizing the magnet preparatory to advancing the wipers of SQ^1 to the third or switch-through position. When the relay 605 terminates the pulse the control equipment CR^1 goes through its switch-through function in the usual manner, and the switching relay 306 of the finder F^1 is energized to connect with the calling line. Since the line 00 is not calling at the time, the circuit of the line relay of the selector S^1 will not be closed and the release relay 304 will not be energized to return holding ground to the switching relay 306, whereupon relay will restore after a brief interval and restore the finder F^1 to normal in the well known manner. If the connector calls the line A^2 after the vertical impulse of the finder number has been determined before the rotary impulse is determined the finder will step up to the level containing the contacts of the calling line but will rotate past the particular contacts of that line. If the connector calls after the vertical and rotary have both been determined, but before the finder F^1 switches through, relay 306 of the finder cannot deenergize to switch through. In this case the wipers of F^1 will be positioned on the contacts of the line A^2 and the private wiper 280 will encounter a ground from the connector over the normal to conductor 250, that ground reversing conductor 274 to springs 323 and its break contact, springs 328 and its break contact, through the resistance 315 to grounded battery, short circuiting the winding of relay 306 to prevent its energization to switch the finder through to the busy calling line. The equipment CR^1 will go through its regular cycle of operation, and return to its normal position, deenergizing relay 603 which completes the release magnet circuit of the finder F^1 , that magnet energizing to release the finder to its normal position.

Continuous vertical pulsing.

In case a fault develops in the equipment CR^1 such as a fault in the circuit of wiper 814,

it would be impossible to stop the vertical motion of the shaft of finder F^1 since the counting circuit would be incomplete. In this case the shaft would be stepped up ten steps, and 5 the magnet would be again energized to attempt the stepping to the eleventh step. Mechanically the shaft of the finder F^1 cannot be raised to the eleventh step and the vertical magnet 312 would not become fully energized 10 on the eleventh step. Springs 330 would not be closed and the circuit through the left-hand winding of relay 605 would remain open leaving that relay in its normal position. After a definite interval relay 606 would 15 energize and close the circuit of switching relay 601, and to restore the control equipment CR^1 to normal. The operation of relay 601 would switch the start circuit of the call then in progress to the group B equipment, that 20 equipment functioning properly would pick it up irrespective of the operation of CR^1 . If the trouble is local to the equipment CR^1 all calls routed to it will be switched in a similar manner. The control equipment CR^2 is 25 of course provided with a similar arrangement.

Continuous rotary pulsing.

In case of trouble in a circuit completed 30 through wiper 710 of the switch RSA, the rotary pulse delivered by the equipment CR^1 would not be terminated at the proper time and the switch would be rotated indefinitely if certain means were not provided to stop it. 35 Mechanically the finder F^1 can be continuously operated in a rotary direction, that is the rotary magnet 313 will be fully energized for each rotary pulse, so that special circuits must be provided to stop a continuous train 40 of rotary impulses when it gets started. Accordingly, I have provided a stopping circuit, which is closed by the wiper 712 when it engages the contact 712', to energize the relay 606 to cause the equipment CR^1 to switch 45 through and restore to normal. When the switch RSA positions its wipers into their next to normal position, circuits may be traced from ground on springs 644, the lower winding of relay 606, conductor 670, through 50 springs 626 and its break contact, conductor 580 through wiper 712 now engaging contact 712', conductor 577 through the winding of magnet 702 to grounded battery, energizing the relay 606 and holding the magnet 702 in 55 its energized position. The relay 606 closes a circuit from the switching relay 601 which energizes and brings the control equipment CR^1 back to normal in the foregoing manner. CR^2 is provided with a similar arrangement to stop it in case of trouble effecting 60 the wiper 705 of the switch RSB.

The foregoing description of an embodiment of my invention is made by way of example only as there are many modifications 65 and adaptations which can be made by one

skilled in the art without departing from the scope of the invention.

Having thus described my invention what I consider new and desire to have protected by Letters Patent, is pointed out in the appended claims.

What is claimed is:

1. In a telephone system, subscribers' lines divided into groups, a finder equipment normally individual to each of said line groups, 75 means for rendering one of said equipments alternatively accessible to lines of other of said groups, means responsive to a call from one of said lines for operating the equipment normally accessible thereto to connect therewith, and means for releasing said equipment and operating said other equipment if said first operated equipment fails to connect with said calling line.

2. In a telephone system, subscribers' lines divided into groups, a finder equipment normally individual to each of said line groups, means for rendering one of said equipments alternatively accessible to lines of other of said groups, means responsive to a call from 90 one of said lines for operating the equipment normally accessible thereto to connect therewith, and means for releasing said equipment and operating said other equipment if said first operated equipment fails on any of the 95 functions instrumental in connecting with said calling line.

3. In a telephone system, groups of lines each having finder equipments which function normally individual to the associated line group, means responsive to a call from one of said groups for operating its associated finder equipment and preparing circuits over which the equipment of another group may be operated to pick up a second call 105 from the same group, and means responsive to the completion of said first call for destroying said prepared circuits and restoring said first operated equipment to normal 110 if there is another idle finder in the group.

4. In a telephone system, groups of lines each having finder equipments which function normally individual to the associated line group, means responsive to a call from one of said groups for operating its associated finder equipment and preparing circuits over which the equipment of another group may be operated to pick up a second call from the same group, means responsive to the completion of said first call for destroying said prepared circuits and restoring said first operated equipment to normal if there is another idle finder in the group, and means responsive to an all finders busy condition of 115 said equipment for maintaining said circuits prepared after said first call is completed.

5. In a telephone system, groups of lines each having finder equipments which function normally individual to the associated line group, means responsive to a call from 120

one of said groups for operating its associated finder equipment and preparing circuits over which the equipment of another group may be operated to pick up a second call 5 from the same group, means responsive to the completion of said first call for destroying said prepared circuits and restoring said first operated equipment to normal if there is another idle finder in the group, and means responsive to a fault which prevents the equipment used for said first call from restoring to normal for maintaining said circuits prepared.

6. In a telephone system, lines divided into 15 two groups, finder equipment comprising two groups of finders and associated control equipments, the first finder group being normally accessible to the first of said line groups and alternatively accessible to the second of said 20 line groups, the second of said finder groups being normally accessible to the second line group and alternatively accessible to the first of said line groups, a start circuit for each of said line groups, means responsive to a call 25 from one of said lines for energizing the corresponding start circuit to start a finder of the normally accessible group, means responsive thereto for altering said start circuit preparatory to starting a finder of said alternatively accessible group, means responsive to a second call before said first is completed, and operative after said first finder has performed a certain cycle of its functions, for 30 energizing said altered start circuit to start a finder of said alternatively accessible group.

7. In a telephone system, two groups of lines, finder equipment, two marking means in each equipment one operated in response to a call originating on a line in the corresponding group to mark that line in the equipment, the other operated in response to a call originating on a line in the other group to the operation of either marking means to direct the finder equipment to the marked 45 line.

8. In a telephone system, two groups of lines, finder equipment, two marking relays in said equipment, means for operating one of said relays in response to a call from a line in the first group for marking that line in the equipment, means for operating said other relay in response to a calling line in the second group to mark that line in the equipment, and means responsive to the operation of either relay for directing said equipment to marked line.

9. In a telephone system, groups of lines, finder equipments, one for each line group, a starting circuit between each line group and the associated finder equipment, two marking relays in each equipment, means responsive to a call on one of said lines for energizing the first of the marking relays of the associated equipment over the associated start circuit, a start relay in each of said equip-

ments, means responsive to the energization of said marking relay for energizing the start relay of that equipment and for locking said energized relays together in a series circuit, means also responsive to the energization of 70 said marking relay for disconnecting the associated start circuit relay from that equipment, means responsive to the energization of said start relay for operating that equipment into connection with said calling line, and 75 means for breaking said locking circuit and for extending said start circuit to the second marking relay of another finder equipment.

10. In a telephone system, groups of lines, 80 finder equipments, one for each line group, a start circuit between each line group and the associated finder equipment, two marking relays in each equipment, means responsive to a call on one of said lines for energizing the first of the marking relays of the associated equipment over the associated start circuit, a start relay in each of said equipments, means responsive to the energization of 85 said marking relay for energizing the start relay of that equipment and for locking said energized relays together in a series circuit, means also responsive to the energization of said marking relay for disconnecting the associated start circuit relay from that equipment, means responsive to the energization 90 of said start relay for operating that equipment into connection with said calling line, and means for breaking said locking circuit, a switching relay and means for energizing it to open said locking circuit and to extend said 95 start circuit to the second marking relay of another finder equipment.

11. In a telephone system, group of lines, 105 finder equipment and start wire normally connected between the two, a second group of lines, a second finder equipment and a second start wire between the two, said finder equipments comprising control mechanisms and finders which are first choice to the corresponding line group and second choice to the 110 other line group, means responsive to a call in the first group for starting said first equipment over said first start circuit, means for switching said first start circuit to said second equipment when said call has progressed through to a certain stage in said first equipment, and means responsive to a second call in the first group for starting said second equipment over said first start circuit provided there are no calls in said second group 115 at the time.

12. In a telephone system, a first group of 125 lines, a first finder equipment and a first start wire normally connected between the two, a second group of lines, a second finder equipment and a second start wire between the two, said finder equipments comprising control mechanisms and finders which are first choice to the corresponding line group and second choice to the other line group, 130

- means responsive to a call in the first group for starting said first equipment over said first start circuit, means for extending said first start circuit to said second equipment 5 when said call has progressed through a certain stage in said first equipment, means responsive to a call in the second line group for operating the second equipment and for opening said extended first start circuit, and 10 means responsive to a second call in the first line group for closing said first start circuit to which ever finder equipment first restores to normal.
13. In a telephone system, a first group of 15 lines, a first finder equipment and a first start wire normally connected between the two, a second group of lines, a second finder equipment, and a second start wire between the two, said finder equipments comprising control mechanisms and finders which are first choice to the corresponding line group and second choice to the other line group, means responsive to an all finders busy condition in said first finder equipped for shifting said 20 first start circuit to said second equipment, and means responsive to a call in said first line group for operating said second equipment to connect thereto.
14. In a telephone system, a plurality of 25 groups of switching mechanisms, a control equipment for each group, each control equipment having normal access only to its associated group of switching mechanism, and means for rendering the switching mechanism of another group accessible to each control equipment.
15. In a telephone system, two groups of 30 finders, a control equipment, a finder allotter for associating said control equipment with the finders of one of said groups in order, means normally effective to prevent said allotter from associating said control equipment with finders in the second of said groups, and means for rendering said first means ineffective to render said latter finders accessible through said allotter.
16. In a telephone system, two groups of 35 finders, a control equipment associated with each group of finders, allotters for associating the control equipments with their respective finders one at a time, said groups normally operating independent of each other, and means for disassociating one of said control equipments and for combining said finder groups as one group under the control of the other control equipment.
17. In a telephone system, two groups of 40 finders, a control equipment associated with each group of finders, allotters for associating the control equipments with their respective finders one at a time, said groups normally operating independent of each other, means for disassociating one of said control equipments and for combining said finder groups as one
- group under the control of the other control equipment, and a manual key for disassociating one of said control equipments and for combining said finder groups as one group under the control of the other control equipment. 45
18. In a telephone system, first and second line groups, first and second finder groups, first and second control equipments, an all finders busy relay in each equipment normally energized over a circuit included in all of the finders of the respective groups, starting means through which a first group calling line operates the first equipment to control a first group finder to connect with said line, means responsive to the operation of the last 50 idle finder of the group for deenergizing said relay, means responsive to the deenergization of said relay for altering said starting means so that said second equipment is responsive to a calling line in either line group to control a second group finder to connect therewith. 55
19. In a telephone system, first and second line groups, first and second finder groups, first and second control equipments, an all finders busy relay in each equipment normally energized over a circuit included in all of the finders of the respective group in multiple, starting means through which a first group calling line operates the first equipment to control a first finder to connect with said line, means responsive to the operation of the last 60 idle finder of the group for deenergizing said relay, means responsive to the deenergization of said relay for altering said start means so that said second equipment is responsive to calling lines in either line group to control a second finder to connect therewith. 65
20. In a telephone system, first and second line groups, first and second finder groups, first and second control equipments, an all finders busy relay in each equipment normally energized over a circuit included in all of the finders of the respective group in multiple, starting means through which a first group calling line operates the first equipment to control a first group finder to connect with said line, means responsive to a deenergization of said relay for altering said start means so that said second equipment is responsive to a calling line in either line group to control a second group finder to connect therewith. 70
21. In a telephone system, groups of subscribers' lines, finder groups, control equipments, means responsive to call from a line in one group for starting a finder in one group under the control of the one control equipment to connect with the calling line, and means responsive to another call in the same group for starting a finder in another group under the control of another control equipment to connect with the other calling line. 75
22. In a telephone system, groups of sub-

- scribers' lines, finder groups, control equipments, means responsive to a call from a line in one group for starting a finder in one group under the control of the one control equipment to connect with the calling line, means responsive to another call in the same line group for starting a finder in another group under the control of another control equipment to connect with the calling line, 5 and means for starting a finder of said first group under the control of said latter control equipment to connect with another calling line of the same line group. 10
23. In a telephone system, groups of subscribers' lines, finder groups, control equipments, means responsive to a call from a line in one group for starting a finder in one group under the control of one control equipment to connect with the calling line, and 15 means responsive to a second call in the same group started before said control equipment returns to normal for starting a finder of another group under the control of another control equipment, to connect with the calling line. 20
24. In a telephone system, groups of subscribers' lines, finder groups, control equipments, means responsive to a call from a line in one group for starting a finder in one group under the control of the one control equipment to connect with the calling line, means for starting a finder of another group under the control of another control equipment to connect with a calling line of another group, and means responsive to a second call 30 in the first mentioned line group for starting the control equipment that restores to normal first, to control a finder of its group to connect with the calling line. 35
25. In a telephone system, groups of subscribers' lines, finder groups, control equipments, means responsive to a call from a line in one group for starting a finder in one group under the control of one control equipment to connect with the calling line, and means responsive to an all finders busy condition in that finder group for rendering another control equipment responsive to another call in the same line group to control a finder of another group to connect with the calling line. 45
26. In a telephone system, groups of subscribers' lines, finder groups, control equipments, means responsive to a call from a line in one group for starting a finder in one group under the control of the one equipment to connect with the calling line, and means responsive to a faulty operation of the first equipment for releasing it and for rendering the second control equipment responsive to said 55 first line group call to control a second group finder to connect with said calling first group. 60
27. In a telephone system, groups of subscribers' lines, finder groups, control equipments, means responsive to a call from a line 65 in one group for starting a finder in one group under the control of the one control equipment to connect with the calling line and means responsive to the blowing of a fuse in that control equipment for rendering another control equipment responsive to calls in 70 that line group to control finders of another group to connect with the calling lines of that line group. 75
28. In a telephone system, groups of subscribers' lines, finder groups, control equipments, means responsive to a call from a line in one group for starting a finder in one group under the control of the one control equipment to connect with the calling line, and means responsive to a faulty operation of said 80 finder for releasing it and the control equipment and for rendering another control equipment responsive to said call to control a finder of another group to connect with said calling line. 85
29. In a telephone system, first and second groups of lines, first and second finder groups for connecting trunk lines with a calling one of said lines, the finders of said first group normally serving said first line group 90 and the finders of said second group normally serving said second group of lines, means for rendering said second group of finders responsive to a call in the first group of lines and for rendering said first group of finders responsive to a call in the second group of lines, first and second discriminating tone sources by means of which the line group of a calling line is distinguished over said trunk lines, and means for applying the 95 first tone to said trunk when a first group line is calling regardless of which finder connects the line to a trunk. 100
30. In a telephone system, first and second groups of lines, first and second finder groups for connecting a trunk line with a calling one of said lines, said first finder normally serving said first line group and said second finder normally serving said second line group, means for rendering said second 105 finder responsive to a call in the first group and for rendering said first finder responsive to a call in the second group, first and second discriminating tone sources by means 110 of which the line group of a calling line is distinguished over said trunk line, switching relays energized to permit said finders to connect with lines in the line group other than that which they normally serve, and means controlled by said relays for applying the corresponding tone to the trunk regardless of which finder group connects the calling line to the trunk. 115
31. In a telephone system, a finder switch, a sending mechanism comprising a pulsing device and a counting mechanism, magnets in said finder switch and in said counting mechanism, armatures for said magnets, 120
- 125

- means for closing parallel circuits from said pulsing device to said magnets to energize them, and means controlled jointly by the armatures of said magnets in their energized 5 positions to open said circuits.
32. In a telephone system, a finder switch, a sender for transmitting impulses to said finder, a pair of counting switches for counting the impulses delivered to said finder, each 10 of said counting switches containing a magnet, restoring circuits for said counting switches including interrupter springs operated by their respective magnets, means for closing said restoring circuits to operate said 15 magnets to move the switches toward their normal positions, and means responsive to the positioning of both of said switches adjacent to their normal positions for opening said restoring circuits.
33. In a telephone system, a finder switch, a sender for transmitting impulses to said finder, a pair of counting switches for counting the impulses delivered to said finder, each 20 of said counting switches containing a magnet, restoring circuits for said counting switches including interrupter springs operated by their respective magnets, means for closing said restoring circuits to operate said 25 magnets to move the switches toward their normal positions, means responsive to the positioning of one of said switches adjacent to its normal position for energizing its magnet independently of said restoring circuit, means 30 responsive to the positioning of the second of said switches adjacent to normal for energizing its magnet independent of said restoring circuit, and means responsive to the energization of both of said magnets for opening 35 said restoring circuit.
34. In a telephone system a finder switch, a sender for transmitting impulses to said finder, a pair of counting switches for counting the impulses delivered to said finder, each 40 of said counting switches containing a magnet, restoring circuits for said counting switches including interrupter springs operated by their respective magnets, a differential relay energized through one winding and operated to close said restoring circuits 45 to move said switches toward their normal positions, and means responsive to the positioning of both of said switches adjacent to their normal positions for closing a circuit to the other winding of said relay to energize it 50 to restore the relay to opening said restoring circuits.
35. In a telephone system, a group of finders each containing a release magnet, a common control equipment, means for associating said equipment with said finders one 55 at a time, means for operating said finders, off-normal springs operated when a selected finder moves off normal to prepare a point in the circuit of its release magnet, and means in said control equipment for prevent- 60 ing the completion of said circuit until said control equipment restores to normal.
36. In a telephone system, a group of finders each containing a release magnet, means for seizing and operating said finders one at 65 a time under the control of a common control mechanism, means for preparing circuits for said magnets when their respective finders are moved out of their normal positions, means in each finder for subsequently closing another point in the said circuits, and means common to said finders for completing 70 said circuits when said control equipment is in its normal position.
37. In a telephone system, a finder having 75 a magnet, a sender, a counting switch having a magnet, means in said sender for simultaneously closing a circuit to said finder magnet and a circuit to said counting switch magnet, and means controlled by the complete 80 energization of both of said magnets for opening said circuits.
38. In a telephone system, a finder switch containing a magnet, an impulse sender, a counting switch having a magnet, means in 85 the sender for closing the circuits of the finder magnet and the counting switch magnet, a relay having windings, a circuit for one winding of said relay completed by the armature of said finder magnet in its energized position, a circuit for the other winding of said relay completed by the armature of said counting switch magnet in its energized position, said relay operating when 90 both its windings are energized, and means 95 controlled by said relay for opening the circuits closed by said sender.
39. In a telephone system, line groups, groups of finders and control equipments for controlling the finders, a sender in each of 100 said equipments containing an impulse terminating relay, a start relay and a slow operating relay, means responsive to a call on one of said lines for energizing said start 105 relay to start said finder and equipment, means for subsequently energizing said impulse terminating relay, means responsive to the energization of said start relay for closing a circuit through contacts on said terminating relay to said slow operating relay, 110 said slow operating relay energizing after a definite interval if said terminating relay is not energized meanwhile, and means controlled by said slow relay in its energized position for releasing said finder and control 115 equipment and for rendering another finder and control equipment responsive to said call.
40. In a telephone system, groups of lines, finders and equipments normally individual to each of said groups, an all finders busy relay in each equipment said relay being maintained energized over a circuit jointly closed by the idle ones of said finders, a switching relay in each of said equipments, a main fuse for each equipment through which 120 125 130

battery is supplied to all of the devices in that equipment except said switching relay, a separate fuse for said switching relay, said all finders busy relay deenergizing responsive to the blowing of said main fuse regardless of the idle condition of any of the finders of that group, and means responsive

to the deenergization of said busy relay for energizing said switching relay to render another equipment responsive to subsequent calls from that line group. ¹⁰

In witness whereof, I hereunto subscribe my name this 3d day of May, A. D. 1926.

RUDOLPH F. STEHLIK.
